CENTRALIZED TRAFFIC CONTROL SYSTEM FOR RAILROADS

Frank T. Pascoe, Scott Township, Allegheny County, Pa., assignor to Westinghouse Air Brake Company, Wilmerding, Pa., a corporation of Pennsylvania

Filed Feb. 4, 1959, Ser. No. 791,185
43 Claims. (Cl. 246—5)

My invention relates to centralized traffic control systems for railroads, and particularly to control systems of this type in which a large number of railway signals and track switches at separate field stations are controlled from a control office over a single line circuit, and in which the same line circuit is employed to indicate at the control office the positions assumed by the switches and signals at the various field stations. More particularly, my invention relates to means at the control office for selecting each individual field station and establishing the commands normally referred to as controls, to be transmitted to each selected station.

The means heretofore usually employed for the selection of field stations to which controls are to be transmitted, and for establishing the controls to be transmitted to the selected stations, consists of a group of control levers and push buttons provided for each field station and mounted on a control machine which includes a miniature track diagram of the track layout of the railway territory to be controlled. For the purpose of establishing correspondence between each group of control levers and push buttons and the corresponding field station on the miniature track diagram, the diagram is designed so that each respective field station appears on the diagram in a position relative to its respective group of control devices. The spacing of the field stations on the track diagram and the size of the control machine are, therefore, controlled by the space on the machine required for mounting the control devices. Since it is desirable that all the control devices be in convenient reach of an operator seated at the control machine, it is apparent that the railway territory that can be conveniently controlled from a single conventional control machine is limited, due to the space required for the control levers and push buttons.

In order to reduce the size of the control machine required for control of a section of railway territory, or in order to increase the size of the territory that may be conveniently controlled from a control machine, it is proposed to remove the control levers and other control devices from the control machine, and to provide a single group of control devices on a control panel or keyboard for selecting the individual field stations and establishing the controls to be transmitted to each selected station. By the removal of the control devices from the control machine, the miniature track diagram thereon may be further miniaturized and vertically tiered to provide a reproduction of a section of railroad territory of a maximum size. The size of the railroad territory that may be thus represented is limited only by the operator's ability to readily read station and other designations appearing on the diagram.

In the above described type of centralized traffic control systems, requiring only a single line circuit between the control office and field locations for transmission of both controls and indications, a selective communication system of the code type is employed for the remote control system. This type of communication system is well known in the art and may, for example, be the type of system shown in Letters Patent of the United States, No. 2,698,425, issued December 28, 1954, to Alfred B. Miller, for a Remote Control System, which

2

system is illustrated and described in a publication of the Union Switch & Signal Division of Westinghouse Air Brake Company, of Swissvale, Pa.; entitled "Manual No. 514," revised in September 1956.

5 In the type of communication system as outlined above, it is recognized that a group of control codes can be transmitted from the control office to only one field station at a time, that only one group of indication codes can be transmitted from a field station to the control office at any one time, and that a group of control codes cannot be transmitted to a field station when another field station is transmitting a group of indication codes. It is thus apparent that, because control codes are being transmitted to a field station or indication codes are being received from a field station, there may be a time delay 10 between the initiation of a group of control codes for another field station and the transmission of this group of codes to this other field station.

When a single group of control devices mounted on a 20 control panel or keyboard is employed for initiating control codes to be transmitted to the various field stations, it is desirable, to avoid time delays, that the control codes for one field station may be initiated and that the panel may be immediately available for the initiation of control codes for another field station. To accomplish this availability of the control panel, and because of the above described time delay that can occur between the initiation of a group of control codes and the transmission of these codes to their respective field station, it is necessary to provide a memory system for the control codes initiated for transmission to each field station. In the conventional type of control machine, where a group of control levers is provided for each field station, the control devices themselves provide the memory system because the levers may be manipulated to various positions and allowed to remain in said positions until the control codes established by the positions of the control devices are transmitted to the respective field location. However, in employing a keyboard or control panel of the type described, it is readily recognized that the control devices on the panel are not always available to provide the necessary memory system since the control devices on the panel are employed, at various times, to establish control codes for all the field stations in the controlled railroad territory. A group of memory relays for each field station is, therefore, required in the control office for storing the control codes to be transmitted to each respective field station. When as in the usual centralized traffic control system, the field stations are relatively 30 numerous, and when the number of functions at some field stations is relatively high, the number of memory relays required at the control office may be economically unjustifiable, thereby nullifying any economic advantage obtained by the reduction in size of the track diagram and the control machine, or the increase in size of the railroad territory that may be conveniently controlled by a single operator at a single control panel.

It is accordingly the principal object of my invention to eliminate the necessity for the memory relays in systems of the class described, wherein a single group of control devices at a control office is employed for controlling a group of functions at each of a plurality of field locations.

It is another object of my invention to provide new 60 and novel means for establishing command or control codes to be transmitted from a control office to the various field stations in a centralized traffic control system for railroads.

Other objects and characteristic features of my invention will become apparent as the description proceeds.

In accomplishing the foregoing objects of my invention, I utilize the indicating relays, normally provided at

the control office for indicating the condition of switches and signals at the various field locations, as control storage or memory relays, in addition to their usual use as indication relays. The manner in which this is done will become apparent hereinafter as the description proceeds.

One form of apparatus embodying my invention will now be described and the novel features thereof will then be pointed out in claims.

In the drawings, FIG. 1a is a diagrammatic view showing an illuminated track diagram of a track layout of a typical siding location in centralized traffic controlled railroad territory. For purposes of simplification of the description, only two field stations, one at each end of the siding are illustrated. FIG. 1b shows the circuit arrangement for the illumination of the indication lamps shown only diagrammatically in FIG. 1a but which will in actual practice be mounted in the diagram of the track layout illustrated in FIG. 1a. The association between the filaments of a various lamps shown in FIG. 1b and their respective location in the track diagram shown in FIG. 1a is believed readily apparent but will be described in more detail as the description proceeds. It is also believed readily apparent that the illustrated track diagram is so located in the control office as to be in convenient view of the dispatcher or operator manipulating various controls to be transmitted to the field locations shown.

FIG. 2 of the drawings shows two groups of push buttons which are located on a control panel or keyboard and are employed by the operator to select each field station, or location to which control codes are to be transmitted. FIGS. 3a, 3b and 3c show the function control push buttons and a series of relays which repeat the manipulations of the push buttons. These push buttons are also located on the control panel along with the station or location selection push buttons.

FIG. 4a shows the manner in which contacts of indication relays in the control office are employed for transmission of the function control codes to the field locations. The apparatus shown on the left-hand side of the arrows is located in the control office and the apparatus shown on the right-hand side of the arrows is located at the field locations, the relays shown on the right-hand side comprising the usual final stick relays at the field locations. FIGS. 4b, 4c and 4d show several relays employed in the code control system used for the illustration of my new invention and will be further described later on in the specification.

FIGS. 5, 6 and 7 show the manner in which the indication relays are manipulated to store control codes, and also the manner in which these relays are employed to repeat the positions of various relays at the field locations to indicate at the office the condition of the field apparatus. Similarly as in FIG. 4a, the apparatus shown on the left-hand side of the arrows in FIGS. 5, 6 and 7 is located at the control office, and the apparatus shown on the right-hand side of the arrows is located at the field locations.

It is expedient to point out at this time that energy for operation of the apparatus shown in the drawings is furnished by suitable sources of direct current at each location, such as a battery of proper voltage and current. For sake of simplicity these sources of current are not shown in the drawings, but the positive and negative terminals of each source are identified in each instance by the reference characters B and N, respectively.

It is also expedient to point out at this time that the form of apparatus embodying my invention and described herein is illustrated as employing a communication system of the type shown in aforementioned Letters Patent of the United States, No. 2,698,425, issued to Alfred B. Miller. However, it is to be understood that any type of communication system may be employed in conjunction with the apparatus of my invention, and it is not in-

tended that my invention is for use only with the system of the said Miller patent.

Referring now to FIG. 1a, the location at the west or left-hand end of the passing siding illustrated on the illuminated miniature track diagram is designated location 35 and is assigned the field station selection or code numeral 235. The location at the east or right-hand end of the siding is designated location 36 and is assigned the field station selection or code number 236. The coincidence between the two digits of the location designation numerals and the last two digits of the field station code numerals is indicative of nothing, but the similar numerals were chosen to assist in avoiding confusion in the description of the operation of the apparatus of my invention. The code control communication system of the aforesaid Miller patent is a 35 station system or capable of transmitting controls and indications to and from 35 field stations; but, by employing additional sets of the communication system equipment, the number of field stations associated with a single control panel is virtually unlimited. However, for purposes of this description it is assumed that field station 235 at location 35 and field station 236 at location 36 are both controlled by the same code control communication system.

The track switch at location 35 in FIG. 1a is designated 35-1W and has normal and reverse indication lamps designated NKE and RKE, respectively. The signal at said location for governing train movements to the right into the siding area is designated 35-2R and has two indication lamps designated AKE and BKE. The signal for governing train movements to the left out of the main track in the siding area is designated 35-2LA, and the signal for governing train movements to the left out of the siding track is designated 35-2LB. Each of these signals also has two indication lamps, each pair also being designated AKE and BKE; however, by the location of the said signal indication lamps on the track diagram it is readily recognized with which signal each pair of lamps is associated.

The track switch at location 36 in FIG. 1a is designated 36-1W and also has normal and reverse indication lamps designated NKE and RKE, respectively. The signals at this location are designated 36-2RA and 36-2RB, and 36-2L, controlling train movements to the right or left as indicated by the letter R or L included in their designations. Each of these signals also has a pair of indication lamps each designated AKE and BKE. The indications displayed by the signal indication lamps will be described later on in this description.

The filaments of the above described indication lamps are shown in FIG. 1b and are designated by the designation of the signal or switch with which they are associated suffixed by the designation of the respective indication lamp. For example, the filament of the AKE indication lamp for signal 35-2LA (FIG. 1a) is designated 35-2LAAKE and the filament of the NKE indication lamp for switch 36-1W (FIG. 1a) is designated 36-1WNKE. The association between the filaments of the lamps shown in FIG. 1b and the lamps designated on the track diagram in FIG. 1a is, therefore, readily apparent. The filaments of the lamps are normally deenergized and therefore the track diagram is normally dark. The circuits for energization of the lamp filaments will be described hereinafter in the description.

There is also shown in FIG. 1b, a code transmitter relay designated by the reference character CTR. As is obvious the terminals of this relay are connected to terminals B and N of the battery and the relay is, therefore, constantly operating to periodically open and close its front contacts *a*. These relays and their operation are well known in the art and any type of such relay may be employed. Terminal B of the battery is connected to the movable portion of contact *a* of relay CTR and a form of coded energy designated CB appears at the front point of contact *a* of the relay. This coded energy is employed to provide additional indications by intermit-

tently flashing the indication lamps AKE, BKE, NKE and RKE under conditions that will hereinafter be described.

FIG. 2 of the drawings shows the field station selection push buttons which are located on the keyboard or control panel and the circuit arrangement controlled by the push buttons. As previously set forth, two groups of push buttons are provided. The first group comprises the tens digit push buttons which establish the tens digit of a field location designation, such for example, as the digit 3 in the numeral 35 employed for designation of field location 35 illustrated in FIG. 1a; or in the designation for a field location 21, not shown in the drawings, the digit 2 in the numeral 21 employed for the designation of such a field location. The second group of push buttons comprises the unit digit push buttons which establish the unit digits of field location designations, such as the digit 5 or 1, respectively, in the examples set forth above. This group of push buttons are designated 0PB through 9PB for the unit digits 0 through 9, respectively.

For purposes of illustration of my invention only three tens digit push buttons are shown in FIG. 2 and, by employing these in conjunction with the ten unit digit push buttons, a total of 39 field stations or locations may be selected (omitting the use of 0PB push button alone for selecting a field station). These three tens digit push buttons are designated 1DPB, 2DPB and 3DPB for selecting the tens digits 1, 2 and 3, respectively, as is obvious. It is apparent that, by providing 9 tens digit push buttons for use in conjunction with the ten unit digit push buttons provide, a total of 99 field stations could be selected (again omitting the use of push button 0PB alone for selecting a field station). It is also apparent that by providing a third or hundreds digit group of push buttons the arrangement shown could be expanded to control a total of 999 field locations (omitting 0PB as before). It should be pointed out that in the arrangement shown in FIG. 2 one of the unit digit push buttons 1PB through 9PB only would be operated to select a field station having the location designations 1 through 9, respectively. No tens digit push button would be operated to select these field locations.

Each of the groups of station selection push buttons 1DPB through 3DPB and 0PB through 9PB are of the "stick" type and are interlocked with each other. That is to say, a push button which has been depressed will remain or "stick" in the depressed position until another push button in the same group is depressed or until a cancellation winding or coil, to be described later, is energized. The interlocking feature of the push buttons thus permits only one push button in a group to be depressed at any one time. Such interlocked types of push buttons are well known in the art and the interlocking feature of the push buttons forms no part of my present invention.

Each of the tens digit push buttons 1DPB through 3DPB is shown in the conventional manner as provided with a movable contact member normally closed against a front contact point and having a normally open or back contact point. Each of the unit digit push buttons 0PB through 9PB is shown provided with a series of movable contact members each having only a normally open or back contact point. The arrow heads on the extensions of the push buttons indicate that the buttons must be depressed to close their back contact points or to open their front contact points.

There is also shown in FIG. 2 a cancellation push button designated by the reference character CPB. This push button is of the spring return type as shown in the conventional manner by the letter S on the extension of the push button. The button is provided with a movable contact member having a normally open or back contact point. When the push button is depressed the movable contact member closes against the back contact point, as indicated by the arrow head on the extension of the push button, and when the button is released the button

is returned to its normal position by the aforesaid spring return action, thereby again opening the aforesaid contact. The utilization of this cancellation button will be described hereinafter.

A tens digit cancellation coil or winding designated by the reference character DCC and a unit cancellation coil or winding designated by the reference character UCC are also shown in FIG. 2. These windings or coils, sometimes referred to as "knock-down" coils, control the cancellation of a storage in each respective group of location selection push buttons, which storages are represented by the depressed condition of a push button in each group of push buttons. In other words, each respective cancellation coil, when energized, releases a depressed push button in the respective push button group to permit it to return to its undepressed or normal position. Interlocking types of push buttons provided with cancellation windings or coils are also well known in the art.

A plurality of keyboard or control panel terminals are shown in FIG. 2 by a plurality of circles each enclosing a terminal designation comprising the letter A followed by a numeral, as readily appears. The terminals A1 through A39, if 39 field locations are to be selected at various times, are each connected to a location selection or control relay similar to relays 35LC and 36LC shown in FIG. 2. However, for the purpose of simplification, since only the two field locations 35 and 36 are employed in the description of my invention, only the location selection relays for these field locations 35 and 36 are shown. These relays are designated 35LC and 36LC for said locations 35 and 36, respectively. One terminal of the winding of relay 35LC is connected to terminal A35 of the control panel, and one terminal of the winding of relay 36LC is connected to terminal A36 of the control panel. The other terminals of the windings of the relays are connected to terminal N of the battery. Relays 35LC and 36LC are telephone type relays each having a plurality of front and back contact points, open and closed, respectively, when the winding of the relay is deenergized, and closed and open, respectively, when the winding of the relay is energized. Some of the contacts on these relays are dependent contacts so arranged as to constitute so-called make-before-break or continuity contacts. This type of relay is well known in the art and any such relay having a sufficient number of contacts may be employed for the location selection relays. The make-before-break contacts on the relays are shown with a wiper portion on the end of the movable members of the contacts as is apparent from the drawings (see for example FIG. 5). The manner in which additional location selection relays may be connected to the control panel for the selection of additional field locations is obvious from the above-description and by reference to FIG. 2 of the drawings. The operation of the apparatus for energizing one of the location selection relays 35LC or 36LC will be discussed below.

Control panel or keyboard terminal A111 shown in FIG. 2 is a cancellation control terminal and is utilized in a manner to be hereinafter described.

It is believed expedient, at this time, to describe the manner in which relays 35LC and 36LC are energized to select their respective field locations. Relay 35LC has a pickup circuit which extends from terminal B of the battery in FIG. 2 over the front point of contact *a* of push button 1DPB, the front point of contact *a* of push button 2DPB, the back point of contact *a* of push button 3DPB, thence to the group of unit digit push buttons and over back contact *d* of push button 5PB to terminal A35, and from terminal A35 through the winding of relay 35LC to terminal N of the battery. Relay 36LC has a pickup circuit extending from terminal B of the battery over the front point of contact *a* of 1DPB, the front point of contact *a* of 2DPB, the back point of contact *a* of 3DPB, thence to back contact *d* of unit digit

push button 6PB, terminal A36, and through the winding of relay 36LC to terminal N of the battery. It is thus obvious that when it is desired to energize relay 35LC for selecting field location 35, the operator depresses push buttons 3DPB and 5PB on the control panel. These push buttons, being of the stick type, the described circuit is completed to energize relay 35LC and the relay will pick up and remain up as long as the said push buttons remain depressed. Similarly, when it is desired to energize relay 36LC for selecting field location 36, the operator depresses push buttons 3DPB and 6PB on the control panel, and relay 36LC is energized over its described pickup circuit and picks up and remains up as long as its said selection push buttons remain depressed. It is to be noted that relays 35LC and 36LC cannot be energized simultaneously because push buttons 5PB and 6PB cannot be depressed at the same time due to the previously described inter-locking feature of each group of push buttons. As previously stated the manner of energization of other station selection relays that can be provided is apparent from this description of the control of relays 35LC and 36LC. The circuits controlled by relays 35LC and 36LC will be described hereinafter.

If an incorrect location selection relay is inadvertently energized by the operator depressing an incorrect push button or buttons, a cancellation may be made by depressing the cancellation button CPB. The depressing of button CPB closes an energizing circuit for cancellation or knockdown coils DCC and UCC which may be traced from terminal B of the battery over back contact *a* of CPB in its depressed position and through the coils DCC and UCC in multiple to terminal N of the battery. As previously described, the energization of the cancellation coils permits the depressed push buttons to return to their undepressed position and the field location selection storages on the control panel are cancelled. As will be hereinafter described, automatic cancellation of location selection storages can be accomplished by connecting terminal B of the battery to terminal A111 of the panel. The cancellation circuit from terminal A111 to the cancellation coils is obvious and no detailed description thereof is necessary.

Referring now to FIG. 3a, there is shown a normal switch control push button designated 1NPB, a normal repeater relay 1NP which is energized by the actuation of the normal switch control push button, a reverse switch control push button 1RPB, and a reverse repeater relay 1RP which is energized by the actuation of the reverse switch control push button. The push buttons 1NPB and 1RPB are spring return push buttons mounted on the control panel, each having a normally open back contact, and employed for initiating controls for directing a first switch at a field location to normal and reverse positions, respectively. These push buttons are identical in operation to cancellation push button CPB previously described and no further description of their operation is considered necessary. Relays 1NP and 1RP are conventional telephone type relays, similar to relays 35LC and 36LC previously described, and no further description of these relays is considered necessary except to point out that no make-before-break contacts are provided on these relays.

Terminals A100 and A101 shown in FIG. 3a are terminals on the control panel similar to the terminals shown in FIG. 2, previously described. Terminals B100, B101 and B102 are multiple connection terminals to which circuits for contacts of all field location selection relays are connected. Because, in this illustrated embodiment of my invention, only two location selection relays are necessary, connection to contacts of these two relays only are shown. However, it should be pointed out that, if additional field locations are to be selected from the control panel, an additional connection is made from each of the multiple connection terminals to a contact of each additional location selection relay employed.

Only two switch control push buttons 1NPB and 1RPB are required on the control panel in the embodiment of my invention illustrated, because there is only one switch at each of the field locations 35 and 36. 5 However, in actual practice the number of switch control buttons which will be required on the control panel will depend on the number of switches at the location having the greatest number of switches, two such buttons being required for each switch at that location. Each 10 of these push buttons would also have associated therewith a relay similar to relays 1NP or 1RP (see FIG. 3a) for repeating the switch control push buttons. It is thus apparent that the control panel is so designed as to control all of the functions to be controlled at all of the 15 field locations in a section of railroad territory. During the initiation of the controls for the field location where a less than the maximum number of functions are to be controlled, the extra control push buttons would not perform any function but would be merely in excess of the number required for control of those locations.

Returning to FIG. 3a, relay 1NP has a pickup circuit which extends from terminal B of the battery over the back point of contact *a* of push button 1NPB, terminal A100, the winding of the relay, multiple connection terminal B100, and thence over a multiple circuit comprising two branches, the first branch extending from terminal B100 over front contact *a* of location selection relay 35LC, previously described, and the front point of contact *b* of switch indication relay 35-1RWK, to be described, 25 to terminal N of the battery; and the second branch extending from terminal B100 over front contact *a* of location selection relay 36LC, previously described, and over the front point of contact *b* of switch indication relay 36-1RWK, to be described, to terminal N of the battery. Relay 1NP is provided with a stick circuit 30 which extends from terminal B of the battery over front contact *b* of relay 35LC or over front contact *b* of relay 36LC to multiple connection terminal B101, front contact *b* of relay 1NP, back contact *c* of relay 1RP, the winding of relay 1NP, and over front contact *a* of relay 1NP to terminal N of the battery. Relay 1NP is thus 35 picked up when push button 1NPB is depressed, relay 35LC is picked up, and reverse switch indication relay 35-1RWK is picked up; or when button 1NPB is depressed, relay 36LC is picked up and reverse switch indication relay 36-1RWK is picked up. Relay 1NP when thus energized is maintained picked up by its stick circuit so long as relay 1RP remains deenergized and relay 35LC or relay 36LC remains energized.

Relay 1RP has a pickup circuit extending from terminal B of the battery over back contact *a* of push button 1RPB, terminal A101, the winding of relay 1RP, multiple connection terminal B102, and thence over a multiple circuit comprising two branches, the first branch extending from terminal B102 over front contact *c* of relay 35LC, and over the back point of contact *b* of relay 35-1RWK to terminal N of the battery; and the second branch extending from terminal B102 over front contact *c* of relay 36LC, and over the back point of contact *b* of relay 36-1RWK to terminal N of the battery. Relay 1RP is provided with a stick circuit which extends from terminal B of the battery over front contact *b* of relay 35LC or over front contact *b* of relay 36LC to multiple connection terminal B101, front contact *b* of relay 1RP, back contact *c* of relay 1NP, the winding of relay 1RP, and over front contact *a* of relay 1RP to terminal N of the battery. Relay 1RP is thus picked up when push button 1RPB is depressed, relay 35LC is energized and reverse switch indication relay 35-1RWK is deenergized; or when push button 1RPB is depressed, relay 36LC is energized and reverse switch indication relay 36-1RWK is deenergized. Relay 1RP when thus energized is maintained picked up by its stick circuit so long as relay 1NP remains deenergized and relay 35LC or relay 36LC remains energized. The circuits con-

trolled by contacts of relays 1NP and 1RP will be described later in this description.

There is shown in FIG. 3b, two push buttons designated by the reference characters 2RPB and 2LPB, respectively. Push button 2RPB is the right signal control push button for initiating controls for operating signal or signals 2R at each field location for governing train movements to the right, and push button 2LPB is the left signal control push button for initiating controls for operating signal or signals 2L at each field location for governing train movements to the left. These push buttons are also mounted on the control panel and are of the three position push-pull type with spring return to the center or neutral position. That is, the push buttons each have a normally open back contact which is closed only when the respective push button is depressed and a normally open front contact which is closed only when the respective push button is pulled. The spring arrangements on the push buttons return the buttons to, and normally maintain them in, their center positions in which no contacts are closed. The arrow heads shown on the extensions of the push buttons indicate the direction in which the push buttons must be operated in order to close the respective movable contact members against their respective stationary contact points.

Relays 2RP and 2LP shown in FIG. 3b are right and left repeater relays which are energized by pushing push buttons 2RPB and 2LPB, respectively, while relay 2NP is a normal repeater relay which is energized by pulling either said push button. Relays 2RP, 2LP and 2NP are also conventional type telephone relays similar to relays 35LC and 36LC previously described and no further description of these relays is considered necessary except to say that relays 2RP and 2LP are each provided with at least one make-before-break contact while no such contact arrangement is provided on relay 2NP.

Terminals A112, A114 and A115 shown in FIG. 3b, are terminals on the control panel similar to the previously described terminals having a numeral designation with a letter A prefix. Terminal B109 is a multiple connection terminal similar to terminals B100, B101 and B102 previously described.

Only two signal control push buttons 2RPB and 2LPB are required on the control panel in the embodiment of my invention illustrated because there is only one set of signals (2R and 2L) at each of the field locations 35 and 36. However, in actual practice two signal control buttons would be provided on the control panel for each set of signals at the field location having the greatest number of sets of signals. Each of these push buttons would have associated therewith a relay similar to relay 2RP or 2LP and a relay similar to relay 2NP would also be associated with each set of signals. As previously set forth, it is apparent that the control panel or keyboard is thus designed to control all of the functions to be controlled at all of the field locations. During the establishment of the controls for the field locations where a less than maximum number of functions are to be controlled, some of the control push buttons would not perform any function but are in excess of the number required for control of those locations.

Referring again to FIG. 3b, relay 2RP has a pickup circuit extending from terminal B of the battery over back contact *a* of push button 2RPB, terminal A114, the back point of make-before-break contact *a* of relay 2RP, the winding of relay 2RP, multiple connection terminal B109, and thence over a multiple circuit including in multiple, a front contact *d* of each of relays 35LC and 36LC to terminal N of the battery. Relay 2RP has a stick circuit which extends from terminal B of the battery over the back point of contact *a* of relay 2NP, the front point of make-before-break contact *a* of relay 2RP, the winding of relay 2RP, terminal B109 and thence over front contacts *d* in multiple of relays 35LC and 36LC to terminal N of the battery. It is thus apparent that

relay 2RP is picked up when push button 2RPB is depressed and relay 35LC or 36LC is energized, and sticks up over its stick circuit, including the front point of its own contact *a*, so long as relay 2NP remains released and relay 35LC or 36LC remains energized. Make-before-break contact *a* of relay 2RP insures that relay 2RP will be maintained picked up when contact *a*, transfers from its back to its front contact points in the closing of its stick circuit.

Relay 2LP has a pickup circuit extending from terminal B of the battery, over back contact *a* of push button 2LPB, terminal A115, the back point of make-before-break contact *a* of relay 2LP, the winding of relay 2LP, terminal B109, and thence over a circuit including, in multiple, the front contacts *d* of each of relays 35LC and 36LC to terminal N of the battery. Relay 2LP has a stick circuit which extends from terminal B of the battery over the back point of contact *a* of relay 2NP, the front point of make-before-break contact *a* of relay 2LP, the winding of relay 2LP, terminal B109, and thence over front contacts *d* in multiple of relays 35LC and 36LC to terminal N of the battery. It thus readily appears that relay 2LP is picked up when push button 2LPB is depressed and relay 35LC or relay 36LC is energized, and is maintained picked up by its stick circuit including the front point of its own contact *a*, so long as relay 2NP remains released and relay 35LC or 36LC remains energized. Make-before-break contact *a* of relay 2LP insures that relay 2LP will be maintained picked up during the transfer of the contact *a* from its back contact point to its front contact point.

Relay 2NP has a multiple pickup circuit extending from terminal B of the battery over front contacts *b*, in multiple, of each of push buttons 2RPB and 2LPB, terminal A112, the winding of relay 2NP, terminal B109, and thence through the multiple circuit including a front contact *d* of each of the relays 35LC and 36LC, in multiple, to terminal N of the battery. Relay 2NP has a stick circuit which extends from terminal B of the battery over the front point of its own contact *a*, back contact *b* of relay 2RP, back contact *b* of relay 2LP, the winding of relay 2NP to terminal B109 and thence over the multiple circuit previously traced, including front contacts *d* of relays 35LC and 36LC, to terminal N of the battery. It is readily seen that relay 2NP is picked up by pulling push button 2RPB or 2LPB when relay 35LC or relay 36LC is energized, and is maintained picked up by its stick circuit including the front point of its own contact *a* so long as relays 2RP and 2LP remain released and relay 35LC or 36LC is energized. The circuits controlled by contacts of relays 2RP, 2LP and 2NP will be described later on in this description.

Referring now to FIG. 3c, there is shown the arrangement of circuits and apparatus for storing a code start for transmission of control codes to field locations through the Form 514 code control system previously mentioned. A spring return push button designated by the reference character STPB and having a normally open back contact *a* and a normally closed back contact *b* is provided on the control panel for initiating and cancelling, respectively, code starts. Contact *a* of push button STPB operates in a manner identical to contact *a* of push button CPB previously described and no further description thereof is necessary except to say that contact *a* is closed when push button STPB is depressed. Contact *b* of push button STPB is normally closed and is opened by the pulling of the push button, as designated by arrow head on the extension of the push button at the movable portion of contact *b*. When the push button is released the spring return feature thereof returns contact *b* to its normally closed position as shown.

Relay STP shown in FIG. 3c is a start repeater relay which repeats the manipulation of push button STPB as will be hereinafter described. Relays 235ST and 236ST are the start relays for storing a start for trans-

mission of control codes to field stations 235 and 236, respectively. These relays correspond to relay 234ST shown in circuit diagram drawing D-2547, sheet 14A, located in the back of the aforesaid Manual No. 514 of the Union Switch & Signal Division of Westinghouse Air Brake Company of Swissvale, Pa. It is to be understood that one of these start relays is employed in the control office for each field location controlled from the control panel, but, as only two such locations are employed in the specific example of my invention described herein, I have shown only the two start relays necessary for the example illustrated. It is believed readily apparent that when additional field locations are controlled from the control panel, the additional necessary start relays provided will be arranged in a manner similar to relays 235ST and 236ST shown in FIG. 3c, and controlled in a manner similar to said relays as described below.

Terminals A150 and A151 are terminals on the control panel similar to terminals A100 and A101 shown in FIG. 3a and described above. Terminal A111 shown by dotted lines in FIG. 3a is the identical terminal A111 shown by solid lines in FIG. 2 and is thus shown in order that the circuit connections to terminal A111 may be described. Terminals B211 and B212 are multiple connection terminals similar to terminals B100, B101 and B102 shown in FIG. 3a. Terminals 8A and 17A in FIG. 3c are terminals on the office line coding unit for the Form 514 code communication system employed in my invention and said terminals 8A and 17A correspond to terminals 8A and 17A shown on aforesaid circuit drawing D-2547, sheet 14A. Reference is made to aforesaid Manual No. 514 and to the said circuit drawing in said manual for a complete understanding of the operation of the internal circuits in the said office line coding unit and connected therein to said terminals 8A and 17A.

Relay STP has a pickup circuit which extends from terminal B of the battery over back contact *a* of push button STPB, terminal A150, and through the winding of relay STP to terminal N of the battery. Relay STP has a stick circuit which extends from terminal B of the battery over front contacts *f* of relays 35LC and 36LC, in multiple, multiple connection terminal B211, the back point of contact *b* of relay MP, to be described, front contact *a* of relay STP and through the winding of relay STP to terminal N of the battery. Relay STP is thus picked up whenever push button STPB is depressed and is maintained picked up as long as relay MP remains released and one of the location selection relays remains energized.

The location selection storage cancellation circuit connected to terminal A111 as shown in FIG. 3c extends from terminal B of the battery over front contacts *f* of relays 35LC and 36LC, in multiple, terminal B211, the front point of contact *b* of relay MP, and front contact *b* of relay STP to terminal A111. It is thus apparent that section location storages on the control panel are cancelled when relay MP is picked up as will be described later in this description. Relay STP, as indicated by the arrows drawn through the movable members of the contacts of the relay, is made slightly slow release to insure that relay MP closes the front point of its contact *b* before front contact *b* of relay STP opens. This insures that the cancellation circuit to terminal A111 is completed when the stick circuit over the back point of contact *b* of relay MP to relay STP is opened by the picking up of relay MP.

Relay 235ST in FIG. 3c has a pickup circuit which extends from terminal B of the battery over front contact *c* of relay STP, multiple connection terminal B212, front contact *e* of relay 35LC, the winding of relay 235ST, terminal A151, and back contact *b* of push button STPB to terminal N of the battery. Relay 235ST has a stick circuit including two branches, the first branch extending from terminal B of the battery over

the back point of make-before-break contact *c* of relay 235S, to be described, to front contact *a* of relay 235ST, and the second branch extending from terminal 8A over the front point of make-before-break contact *c* of relay 235S to front contact *a* of relay 235ST, and thence through the winding of relay 235ST to terminal A115 and over back contact *b* of push button STPB to terminal N of the battery. Relay 235ST is thus picked up when relay STP picks up and location selection relay 35LC is energized, and is maintained picked up until push button STPB is pulled or until relay 235S is energized and energy is removed from terminal 8A of the office line coding unit.

Relay 236ST shown in FIG. 3c has a pickup circuit which extends from terminal B of the battery over front contact *c* of relay STP, terminal B212, front contact *e* of relay 36LC, the winding of relay 236ST, control panel terminal A151, and over back contact *b* of push button STPB to terminal N of the battery. Relay 236ST has a stick circuit including two branches, the first branch extending from terminal B of the battery over the back point of make-before-break contact *c* of relay 236S, to be described, to front contact *a* of relay 236ST, and the second branch extending from terminal 8A over the front point of make-before-break contact *c* of relay 236S to front contact *a* of relay 236ST, and thence through the winding of relay 236ST to terminal A151 and over back contact *b* of push button STPB to terminal N of the battery. Relay 236ST is thus picked up when relay STP picks up and is maintained picked up until push button STPB is pulled or until relay 236S is energized and energy is removed from terminal 8A of the office line coding unit. Relays 235ST and 236ST operate in a manner similar to relay 234ST shown in said drawing D-2547, sheet 14A in said Manual No. 514, and reference is made to said Manual for a complete understanding of the operation of the ST relays and the circuits controlled thereby, these relays themselves forming no part of my present invention but being shown in order to make the specification complete.

It is deemed expedient to discuss at this time the apparatus shown in FIGS. 4b, 4c and 4d before further description of the apparatus arrangement of my invention is given. Relay MP shown in FIG. 4b corresponds to relay MP shown in the lower left-hand portion of said drawing D-2547, sheet 14A, and operates in a manner identical to said relay. Relays 235D and 236D in FIG. 4c are similar to relay 234D shown on the right-hand side of sheet 14A of said drawing D-2547. Relays 235S and 236S shown in FIG. 4d are similar to relay 234S shown in the lower right-hand portion of said sheet 14A. These relays shown in said FIGS. 4b, 4c and 4d form no part of my present invention but are shown in order to make this specification complete. It is considered sufficient for purposes of this description to point out that relay MP is the master relay repeater relay employed to repeat the M or master relay of the code communication system. The M relay and thus the MP relay are energized when a control code is to be transmitted by the code system. Relays 235D and 236D are the delivery relays for the code control communication system and pick up to deliver information, received from the respective field location, to the proper indication relays as will be more apparent later in this description. Relays 235S and 236S are the station call relays for field stations 235 and 236 and select the respective station determined by the code combination transmitted by the code control communication system. Reference is made to aforesaid Manual No. 514 for a more complete understanding of the operation of relays MP, 235D, 236D, 235S and 236S.

The code communication circuits for transmitting control codes to the field locations are shown schematically in FIG. 4a. Relays 35-1NRWSR, 35-2LHSR, 35-2RHSR, and 35-1TKSPR are located at field location 35 which is assigned to field station 235 in the code com-

munication system. These relays correspond to relays NRWSR, LHSR, RHSR and TKSPR, respectively, shown in drawing D-2547, sheet 15A, in the back of the aforementioned Manual No. 514. Relays 36-1NRWSR, 36-2LHSR, 36-2RHSR and 36-1TKSPR are located at field location 36 which is assigned to field station 236 in the code communication system. The correspondence between these relays and the similar relays shown on sheet 15A of said drawing D-2547 is readily apparent.

Relays 35-1NRWSR and 36-1NRWSR comprise the final stick relays at the field locations for controlling switches 35-1W and 36-1W respectively, to normal and reverse positions. Relays 35-2LHSR, 36-2LHSR, 35-2RHSR and 36-2RHSR comprise the final stick relays at the field locations for controlling the clearing of left and right signals, respectively, at the field locations. These relays are of the magnetic stick type the contacts of which are operated to first and second positions by an impulse of energy of one polarity or another through their control windings and which remain in the last operated position without energy. Such relays are well known in the art and no further description thereof is necessary. Relays 35-1TKSPR and 36-1TKSPR are conventional neutral relays which are employed in the field to repeat the occupied or unoccupied condition of track sections 35-1T and 36-1T, respectively, represented on the track diagram in FIG. 1a. These relays are energized and deenergized respectively when their associated track sections are unoccupied or occupied.

The circuit arrangement shown on the left-hand side in FIG. 4a shows the arrangement at the control office for controlling the transmission of control codes to the field location. As is apparent, contacts of NWK, RWK, LHK and RHK indication relays are employed to control the transmission of the control codes. The indication relays, contacts of which are shown in drawing FIG. 4a, will be described hereinafter.

The dotted lines between the two sets of terminals shown in FIG. 4a, represent the Form 514 code control communication system previously mentioned and employed in this example of my invention, and no details of this portion of the code control communication system need be shown. The terminals to the left of the dotted lines represent terminals on the office line coding unit, and the terminals to the right of the dotted lines represent terminals on the field line coding units. These units are shown on sheets 14A and 15A, respectively of drawing D-2547 in the aforesaid Manual No. 514.

The code control communication system in the example shown in this description operates in the identical manner to the communication system shown and described in said Manual No. 514, and it is, therefore, considered sufficient for purposes of this description to point out that the code system will transmit a code for controlling a switch control relay to a first position for controlling a switch to its reverse position when positive energy is supplied to terminal 3A of the office line coding unit. Similarly, the code system will transmit code for controlling a switch control relay to a second position for controlling a switch to its normal position when positive energy is supplied to terminal 1A of the office coding unit. Likewise, the code system will transmit a code for controlling signal control relays to a first position for clearing of signals when positive energy is supplied to terminals 5A or 7A, and will transmit a code to control the signal control relays to a second position for controlling signals to stop when no energy is supplied to said terminals 5A or 7A.

The circuit for supplying positive energy to terminal 3A for controlling switch control relay 35-1NRWSR to its said first position, extends from terminal B of the battery over front contact d of station call relay 235S, the front point of contact c of relay 35-1RWK, to be described, and front contact b of relay 35-1NWK, to be described, to terminal 3A. The circuit for supplying positive energy to terminal 1A for controlling switch

control relay 35-1NRWSR to its said second position extends from terminal B of the battery over front contact d of relay 235S, the back point of contact c of relay 35-1RWK, and back contact c of relay 35-1NWK to terminal 1A.

The circuit for supplying positive energy to terminal 5A for controlling signal control relay 35-2LHSR to a position for clearing signal 35-2LA or 35-2LB extends from terminal B of the battery over front contact e of relay 235S, the front point of contact g of relay 35-2LHK to be described, and back contact g of relay 35-2RHK, to be described, to terminal 5A. The circuit for supplying positive energy to terminal 7A for controlling signal control relay 35-2RHSR to a position for clearing signal 35-2R extends from terminal B of the battery over front contact e of relay 235S, the back point of contact g of relay 35-2LHK, and the front point of contact h of relay 35-2RHK to terminal 7A.

The circuit for supplying positive energy to terminal 3A for controlling switch control relay 36-1NRWSR to its said first position extends from terminal B of the battery over front contact d of station call relay 236S, the front point of contact c of relay 36-1RWK, to be described, and front contact b of relay 36-1NWK, to be described, to terminal 3A. The circuit for supplying positive energy to terminal 1A for controlling switch control relay 36-1NRWSR to its said second position extends from terminal B of the battery over front contact d of relay 236S, the back point of contact c of relay 36-1RWK, and back contact c of relay 36-1NWK to terminal 1A.

The circuit for supplying positive energy to terminal 5A for controlling signal control relay 36-2LHSR to a position for clearing signal 36-2L extends from terminal B of the battery over front contact e of relay 236S, the front point of contact g of relay 36-2LHK, to be described, and back contact g of relay 36-2RHK, to be described, to terminal 5A. The circuit for supplying positive energy to terminal 7A for controlling signal control relay 36-2RHSR to a position for clearing signals 36-2RA or 36-2RB extends from terminal B of the battery over front contact e of relay 236S, the back point of contact g of relay 36-2LHK, and front contact h of relay 36-2RHK to terminal 7A.

Referring now to FIG. 5, there is shown the switch indication circuits at field locations 35 and 36 and the switch indication relays in the control office. The terminals shown to the right of the arrows are terminals on the field line coding units at the respective field locations and the circuits shown on the right-hand side of the drawing are the circuits for controlling the indications to be transmitted. Relays 35-1NRWSR and 36-1NRWSR, contacts a of which are shown at the field locations in FIG. 5, are the switch control or final stick relays shown in FIG. 4a, as previously mentioned, for controlling the movements of switches 35-1W and 36-1W to normal and reverse positions. Relays 35-1NWCR, 35-1RWCR, 36-1NWCR and 36-1RWCR, the windings and contacts of which are shown at the field locations in FIG. 5, are switch correspondence or repeater relays which reflect the correspondence between the positions of switch control relays 35-1NRWSR and 36-1NRWSR and the positions of the respective switches 35-1W and 36-1W at field locations 35 and 36, respectively. The control circuits to the windings of these relays are not shown in the drawings but relays 35-1NWCR and 36-1NWCR may be controlled, for example, in a manner similar to relay 3NWC shown in FIG. 1b of Letters Patent of the United States No. 2,532,832, issued December 5, 1950, to Ira F. Cadman, for Approach Lock Release in Railway Signaling Systems. Relays 35-1RWCR and 36-1RWCR are similar to relay 3RWC shown in FIG. 1b of said patent. Such switch correspondence or repeater relays are well known in the art and, since the control of these relays forms no part of my present invention, it is considered sufficient for purposes of this description to point

out that contacts *a* and *b* of relays 35-1NWCR and 36-1NWCR are picked up only when switches 35-1W and 36-1W, respectively, and relays 35-1NRWSR and 36-1NRWSR, respectively, occupy normal positions. Contacts *a* and *b* of relays 35-1RWCR and 36-1RWCR are picked up only when switches 35-1W and 36-1W, respectively, and relays 35-1NRWSR and 36-1NRWSR, respectively, occupy reverse positions. Switches 35-1W and 36-1W, and control relays 35-1NRWSR and 36-1NRWSR, being assumed to normally occupy their normal positions, the contacts of relays 35-1NWCR and 36-1NWCR are shown picked up, and the contacts of relays 35-1RWCR and 36-1RWCR are shown released in FIG. 5.

Terminals 9A and 11A in FIG. 5 are terminals on the office line coding unit in the control office. The dotted lines shown between the terminals on the office line coding unit and the field line coding units represent the Form 514 code control communication system employed in the present illustrated example of my invention. Terminals 9A and 11A are multiple connection terminals as is apparent in FIG. 5 and correspond to terminals 9A and 11A, respectively shown on the right-hand side of sheet 14A of drawing D-2547 in aforesaid Manual No. 514.

Relays 35-1NWK and 36-1NWK are the switch indication relays at the control office which indicate respectively the normal position of switches 35-1W and 36-1W and the corresponding position of their control relays at field locations 35 and 36, respectively. Similarly, relays 35-1RWK and 36-1RWK are switch indication relays indicating, respectively, the reverse position of switches 35-1W and 36-1W and the corresponding position of their control relays at the said field locations. As previously stated, switches 35-1W and 36-1W, and relays 35-1NRWSR and 36-1NRWSR, being assumed to normally occupy their normal positions, relays 35-1NWK and 36-1NWK are shown normally picked up and relays 35-1RWK and 36-1RWK are shown normally released.

Relay 35-1NWK has an indication pickup circuit extending from terminal 9A of the office line coding unit over the front point of make-before-break contact *a* of relay 235D and through the winding of the relay to terminal N of the battery. Relay 35-1NWK has a control pickup circuit extending from terminal B of the battery over front contact *d* of relay 1RP, multiple connection terminal B210, to be described, front contact *g* of relay 35LC and through the winding of relay 35-1NWK to terminal N of the battery. Relay 35-1NWK has a first stick circuit extending from terminal B of the battery over the back point of make-before-break contact *h* of relay 35LC, front contact *a* of relay 35-1NWK, the back point of make-before-break contact *a* of relay 235D, and through the winding of relay 35-1NWK to terminal N of the battery. Relay 35-1NWK has a second stick circuit extending from terminal B of the battery over back contact *d* of relay 1NP, multiple connection terminal B211, to be described, the front point of make-before-break contact *h* of relay 35LC and thence over front contact *a* of relay 35-1NWK and through the remainder of the first stick circuit for relay 35-1NWK, just described, to terminal N of the battery.

Relay 35-1RWK has an indication pickup circuit extending from terminal 11A of the office line coding unit over the front point of make-before-break contact *b* of relay 235D, and through the winding of relay 35-1RWK to terminal N of the battery. Relay 35-1RWK has a control pickup circuit extending from terminal B of the battery over front contact *e* of relay 1RP, multiple connection terminal B212, to be described, front contact *k* of relay 35LC, and through the winding of relay 35-1RWK to terminal N of the battery. Relay 35-1RWK has a first stick circuit extending from terminal B of the battery over the back point of make-before-break contact *h* of relay 35LC, front contact *a* of relay 35-1RWK, the back point of make-before-break contact *b* of relay 235D

and through the winding of relay 35-1RWK to terminal N of the battery. Relay 35-1RWK has a second stick circuit extending from terminal B of the battery over back contact *d* of relay 1NP, terminal B211, the front point of make-before-break contact *h* of relay 35LC and thence over front contact *a* of relay 35-1RWK and through the remainder of the first stick circuit for relay 35-1RWK, just described, to terminal N of the battery.

Relays 36-1NWK and 36-1RWK have pickup and stick circuits similar to those just described for relays 35-1NWK and 35-1RWK, respectively, except including contacts of relays 36LC and 236D and their own front contacts *a*, and no detailed tracing of these circuits is considered necessary.

Terminals B210, B211 and B212 are multiple connection terminals to which, in actual practice, control pickup circuits for the indication relays for each first switch at all field locations are connected, but, only two field locations being illustrated in this described example of my invention, only the control pickup circuits for the indication relays for switches 35-1W and 36-1W are shown in FIG. 5. It is also desired to point out that additional indication pickup circuits are, in actual practice, connected to terminals 9A and 11A for control of indication relays for each first switch at all field locations. However, these circuits are also not shown because in the illustrated example of my invention only two field locations are shown.

The operation and purpose of the circuits shown in FIG. 5 will become more apparent later in this specification in the description of a specific example of the control of one of the switches shown on the track diagram in FIG. 1a.

FIGS. 6 and 7 show the signal indication circuits at the field locations and the signal indication relays at the control office. The terminals shown to the right of the arrows are terminals on the field line coding units at the respective field locations and the circuits shown on the right-hand side of the drawings are the circuits for controlling the indications to be transmitted. Relays 35-2LHSR and 35-2RHSR, contacts *a* and *b* of which are shown in FIG. 6 at the field location 35, are the final stick relays shown in FIG. 4a for controlling the clearing of signals 35-2LA and 35-2LB, and 35-2R, respectively. Relays 36-2LHSR and 36-2RHSR, contacts *a* and *b* of which are shown in FIG. 7 at the field location 36, are the final stick relay shown in FIG. 4a for controlling the clearing of signals 36-2L and 36-2RA and 36-2RB, respectively.

Relays 35-2LRGPR and 35-2RRGPR, the windings and contacts *a* of which are shown at field location 35 in FIG. 6, are signal repeater relays which reflect the condition of signals 35-2LA and 35-2LB, and 35-2R, respectively. The control circuits for the windings of these relays are not shown in the drawings, but such signal repeater relays and their operation are well known in the art. Relay 35-2RRGPR may be controlled for example in a manner similar to relay L58RP shown in FIG. 1b of Letters Patent of the United States No. 2,580,150, issued December 25, 1951 to Earl M. Allen for Route Circuit Network Control Apparatus for Railway Signals. It is considered sufficient for purposes of this description to point out that back contact *a* of relay 35-2LRGPR is open when both signals 35-2LA and 35-2LB indicate stop, and said contact *a* is closed when either of said signals is cleared for a train movement to the left. Similarly, contact *a* of relay 35-2RRGPR is picked up and opens when signal 35-2R indicates stop, and said contact *a* is released and closed when said signal is cleared for a train movement to the right.

Relays 36-2LRGPR and 36-2RRGPR shown at field location 36 in FIG. 7 are signal repeater relays similar to those described above. These relays reflect the condition of signals 36-2L, and 36-2RA and 36-2RB, respectively. Back contact *a* of relay 36-2LRGPR is open when

signal 36-2L indicates stop, and said contact *a* is closed when said signal is cleared for a train movement to the left. Back contact *a* of relay 36-2RRGPR is open when both signals 36-2RA and 36-2RB indicate stop, and said contact *a* is closed when either of said signals is cleared for a train movement to the right.

Relays 35-2LASR and 35-2RASR shown in FIG. 6, and relays 36-2LASR and 36-2RASR shown in FIG. 7 are approach locking relays for signals 35-2L and 35-2R, and 36-2L and 36-2R, respectively. The windings and contacts *a* of these relays are shown in FIGS. 6 and 7 but the control circuits for the windings of the relays are not shown. Such approach locking relays and their operation are well known in the art. Relay 35-2LASR may be controlled, for example, in a manner similar to relay L58ALS shown in FIG. 1b of aforesaid Earl M. Allen Patent No. 2,580,150. It is deemed sufficient for purposes of this description to point out that such relays are normally picked up, and are released when a control code is received at the respective field location for clearing the respective signal or signals. That is, relay 35-2LASR is released when a control code is received at field location 35 for clearing signal 35-2LA or 35-2LB. Relay 35-2RASR is released when a control code is received for clearing signal 35-2R. Similarly, relay 36-2LASR is released when a control code is received at field station 36 for clearing signal 36-2L, and relay 36-2RASR is released when a control code is received for clearing signals 36-2RA or 36-2RB. When an approach locking relay is released and a control code is received for controlling the respective signal to indicate stop, the relay is not picked up until the expiration of a predetermined time delay. This time delay period is often termed the "in time" period of a signal and, as will be described in more detail later in this description, an "in time" indication is transmitted from the respective field location to the control office.

Terminals 13A and 15A in FIG. 6 are terminals on the office line coding unit in the control office. These terminals are also shown by dotted lines in FIG. 7 and it is believed readily understood that they are multiple connection terminals and that both sets of terminals shown are, therefore, the same terminals. The dotted lines shown between the terminals on the office line coding unit and the field line coding units represent, as before the Form 514 code control communication system employed in illustrating and describing my invention. Terminals 13A and 15A in FIGS. 6 and 7 correspond to terminals 13A and 15A respectively, shown on the right-hand side of sheet 14A of drawing D-2547 in aforementioned Manual No. 514 which describes said Form 514 code control system.

Relays 35-2LHK and 35-2RHK (FIG. 6) are the signal indication relays at the control office which indicate respectively, the condition of signals 35-2LA and 35-2LB, and signal 35-2R. Similarly, relays 36-2LHK and 36-2RHK (FIG. 7) are the signal indication relays at the control office which indicate respectively the condition of signals 36-2L, and 36-2RA and 36-2RB. Relays 35-2RHK and 36-2LHK are picked up to indicate that their respective signals are cleared, and relays 35-2LHK and 36-2RHK are picked up to indicate that their respective signals are cleared. Signals 35-2LA, 35-2LB, 35-2R, 36-2L, 36-2RA and 36-2RB, illustrated on the track diagram in FIG. 1a, are assumed to normally be at stop and, therefore, the said signal indication relays are all shown released. Relays 35-2HK and 36-2HK are auxiliary signal indication relays, the purpose of which will become apparent later in this description. These relays are also normally released as shown.

Terminals B200 through B206 shown in FIG. 6 are multiple connection terminals to which the signal indication relays for each first set of signals at all field locations are connected. However, only two field locations being illustrated in the present described example of my invention

tion only two sets of signal indication relays are shown connected to said terminals, and these multiple connections are illustrated by showing said terminals by dotted lines in FIG. 7 of the drawings. It is to be understood that the terminals B200 and B206 shown in this manner in FIG. 7 represent the same terminals B200 through B206 shown by solid lines in FIG. 6.

Relay 35-2LHK has an indication pickup circuit which extends from terminal 13A on the office line coding unit over the back point of contact *e* of relay 35-2RHK, the front point of make-before-break contact *c* of relay 235D, and through the winding of relay 35-2LHK to terminal N of the battery. Relay 35-2LHK has an indication stick circuit extending from said terminal 13A over the front point of contact *e* of relay 35-2RHK, the front point of contact *e* of relay 35-2LHK, the front point of make-before-break contact *c* of relay 235D, and through the winding of relay 35-2LHK to terminal N of the battery.

Relay 35-2LHK has a first control pick-up circuit extending from terminal B of the battery over front contact *b* of relay 2NP, terminal B200, front contact *l* of relay 35LC, the front point of contact *d* of relay 35-2RHK, and through the winding of relay 35-2LHK to terminal N of the battery. Relay 35-2LHK has a second control pickup circuit extending from terminal B of the battery over the front point of contact *c* of relay 2LP, terminal B201, front contact *m* of relay 35LC, the back point of contact *d* of relay 35-2RHK, and through the winding of relay 35-2LHK to terminal N of the battery.

Relay 35-2LHK has a control stick circuit comprising three branches, the first branch extending from terminal B of the battery over the back point of make-before-break contact *n* of relay 35LC to front contact *a* of relay 35-2LHK; the second branch extending from terminal B of the battery over the back point of contact *c* of relay 2RP, terminal B202, the front point of make-before-break contact *n* of relay 35LC to front contact *a* of relay 35-2LHK; and the third branch extending from terminal B of the battery over front contact *o* of relay 35LC, back contact *b* of relay 35-2RHK to front contact *a* of relay 35-2LHK where all three branches merge and extend over front contact *a* of relay 35-2LHK, the back point of make-before-break contact *c* of relay 235D, and through the winding of relay 35-2LHK to terminal N of the battery.

Relay 35-2RHK has an indication pickup circuit extending from terminal 15A of the office line coding unit over the back point of contact *f* of relay 35-2LHK, the front point of make-before-break contact *d* of relay 235D, and through the winding of relay 35-2RHK to terminal N of the battery. Relay 35-2RHK has an indication stick circuit extending from said terminal 15A over the front point of contact *f* of relay 35-2LHK, the front point of contact *f* of relay 35-2RHK, the front point of make-before-break contact *d* of relay 235D, and through the winding of relay 35-2RHK to terminal N of the battery.

Relay 35-2RHK has a first control pickup circuit extending from battery terminal B over front contact *c* of relay 2NP, terminal B203, front contact *p* of relay 35LC, the front point of contact *d* of relay 35-2LHK and through the winding of relay 35-2RHK to battery terminal N. Relay 35-2RHK has a second control pickup circuit extending from battery terminal B over the front point of contact *c* of relay 2RP, terminal B204, front contact *r* of relay 35LC, the back point of contact *d* of relay 35-2LHK, and through the winding of relay 35-2RHK to terminal N of the battery.

Relay 35-2RHK has a control stick circuit comprising three branches, the first branch extending from battery terminal B over the back point of make-before-break contact *s* of relay 35LC to front contact *a* of relay 35-2RHK; the second branch extending from battery terminal

B over the back point of contact *c* of relay 2LP, terminal B205, the front point of make-before-break contact *s* of relay 35LC to front contact *a* of relay 35-2RHK; and the third branch extending from terminal B of the battery over front contact *o* of relay 35LC, the back point of contact *b* of relay 35-2LHK to front contact *a* of relay 35-2RHK where all three branches merge and extend over front contact *a* of relay 35-2RHK, the back point of make-before-break contact *d* of relay 235D, and through the winding of relay 35-2RHK to battery terminal N.

Relay 35-2HK has two indication pickup circuits, the first extending from terminal 13A on the office line coding unit over the front point of contact *e* of relay 35-2RHK and over the back point of contact *e* of relay 35-2LHK to the front point of make-before-break contact *e* of relay 235D, and the second extending from terminal 15A on the office line coding unit over the front point of contact *f* of relay 35-2LHK and over the back point of contact *f* of relay 35-2RHK to the front point of make-before-break contact *e* of relay 235D, where the two pickup circuits merge and extend over the front point of said contact *e* of relay 235D, through the winding of relay 35-2HK, over back contacts *e* of relays 35-2LHK and 35-2RHK, in a multiple circuit, thence over the back point of make-before-break contact *t* of relay 35LC to battery terminal N, or over the front point of said contact *t* of relay 35LC, terminal B206, and back contacts *d* of relays 2RP and 2LP, in a series circuit, to battery terminal N. Relay 35-2HK has a stick circuit extending from battery terminal B over its own front contact *a*, the back point of make-before-break contact *e* of relay 235D, through the winding of relay 35-2HK and thence through said back contacts *e* of relays 35-2LHK and 35-2RHK in multiple, and over its own front contact *b* to terminal N of the battery.

Relays 36-2LHK, 36-2RHK and 36-2HK shown in FIG. 7 have pickup and stick circuits similar to those just described for relays 35-2LHK, 35-2RHK and 35-2HK, respectively, except including contacts of relays 36LC and 236D and their own contacts *a* and *b* and no detailed tracing of these circuits is considered necessary.

As hereinbefore stated, I utilize, in my invention, the above described indication relays as control storage or memory relays, in addition to their usual use as indication relays. I will now describe in general terms the manner in which said relays are actuated to store field function commands or controls, and will later set forth specific examples of the operation of some of the relays in their employment as both field function control storage relays and field function indication relays.

In the usual code control communication system two neutral relays, such as 35-1NWK and 35-1RWK shown in FIG. 5, are employed for indicating the two extreme positions of a switch, and one or the other of the relays is picked up to indicate said switch positions. Both relays are released at the same time only when the switch is in transit from one position to the other, and in the usual systems the two relays are never picked up at the same time. By providing control means for picking up both relays at the same time, it is apparent that a combination is available for establishing a control for operating the switch to one extreme position; and, by maintaining both relays picked up, this control can be stored until it performs its desired function, that is, the operation of the switch to said one extreme position. Similarly, by providing control means for releasing both relays at the same time, it is apparent that a combination is available for establishing a control for operating the switch to the other extreme position; and, by maintaining both relays released, this control can be stored until it performs its desired function, that is, the operation of the switch to said other extreme position. Usually a true "switch-in-transit" indication is provided by the released combination of both said indication relays. By employing this combination of said

relays for storing a control for operating the switch to one extreme position, as set forth above, it at first appears that no means is now available for providing a switch-in-transit indication. However, if establishing and storing a switch control will be assumed to be equivalent to the switch actually being in transit, the said released combination of both indication relays can continue to be employed for providing the switch-in-transit indication when said both relays are released, and the above-described picked-up combination of both relays can be employed for providing said indication when both relays are picked up. Accordingly my invention provides circuits and apparatus arrangements for accomplishing the desired operation described. This arrangement will become more apparent in the specific examples of the operation of my invention set forth hereinafter in this description.

Two neutral relays, such as relays 35-2LHK and 35-2RHK shown in FIG. 6 of the drawings, are employed in the usual code control communication systems for indicating the condition of opposing signals. Both relays are normally released to indicate the normal or stop condition of the signals and each are picked up in said signal systems when their respective signals are cleared. Because opposing signals cannot be cleared at the same time the picked-up combination of both signal indication relays is employed in said usual systems to indicate when the signals are "in time" which occurs, as previously explained, when a signal is cleared and then manually controlled to its stop condition. By providing control means for picking up each said relay when it is desired to clear its respective signal, and maintaining the picked-up relay in said position, means are provided for establishing and storing a signal control to be transmitted to the respective field location. However, it now appears that there are no means at the control office to respond to a signal clear indication being received from the field location. Accordingly, in my invention I have provided an additional signal indication relay, such as relay 35-2HK in FIG. 6 of the drawings, for each set of opposing signals. These relays are so arranged as to be picked up when either left or right signals are cleared and, in combination with a controlled picked-up condition of the LHK or RHK relay, an indication can be provided to indicate which signal is cleared. The picked-up condition of both LHK and RHK relays can continue to be employed for giving an "in-time" indication as hereinafter described.

As discussed in general terms above, I thus provide in my invention means whereby the usual signal indication relays for a set of signals can be employed to store signal controls to be transmitted to the field location of said signals, and in conjunction with one additional relay (HK) for each set of signals, the usual signal indication relays can continue to be employed for indicating the cleared condition of the signals. The arrangement to accomplish this operation will become more apparent in the description of the specific examples of the operation of my invention set forth hereinafter in this specification.

Having thus set forth in general terms the principal features of my invention, I will now describe the operation of the circuit and apparatus arrangements shown in the drawings by specific examples of the selection of a field location; the establishing, storing and transmitting of controls for performing several functions at the selected location; and the receiving of indications from said location of the performance of the controlled functions.

All apparatus is shown in the drawings in its normal condition. Assuming that it is desired to clear signal 35-2LB, shown in FIG. 1a, at field location 35 (field station 235), for a train movement out of the siding in the left-hand or westward direction over switch 35-1W in its reverse position, the control panel operator will first select the field location by depressing push buttons 3DPB and 5PB on the control panel (FIG. 2) in that order. This manipulation will energize location selection relay 35LC over its previously described pickup circuit including back contacts of push buttons 3DPB and 5PB, the relay will

pick up, and, the buttons being stick push buttons as previously described, relay 35LC will temporarily remain picked up. Field location 35 has thus been selected.

The operator will now depress reverse switch control push button 1RPB (FIG. 3a) and left signal control push button 2LPB (FIG. 3b) in that order. The depressing of push button 1RPB momentarily closes back contact *a* of the button, and relay 1RP is energized over its previously described pickup circuit including front contact *c* of location selection relay 35LC and the back point of contact *b* of relay 35-1RWK. Relay 1RP accordingly picks up. The said front contact of relay 35LC prevents the establishment of the switch control before a field location has been selected. The said back contact of relay 35-1RWK permits the establishment of the reverse switch control only when the switch occupies its normal position or is in transit to its normal position. (Similarly the front point of contact *b* of relay 35-1RWK in the previously described pickup circuit for relay 1NP permits the establishment of a normal switch control only when the switch occupies its reverse position or is in transit to its normal position.) Relay 1RP picks up as stated, and is maintained picked up over its previously described stick circuit including its own front contacts *a* and *b*, back contact *c* of relay 1NP and front contact *b* of relay 35LC. Back contact *c* of relay 1NP insures that the stick circuit for relay 1RP is opened when a normal switch control is established, and, if relay 1RP is picked up by the operator inadvertently depressing push button 1RPB when he intended to push button 1NPB, the subsequent depressing of button 1NPB and picking up of relay 1NP will open the stick circuit for relay 1RP at the open back contact *c* of relay 1NP, thereby releasing relay 1RP. The negative terminal of the battery is connected to relay 1NP over the front point of contact *b* of relay 35-1RWK when relay 1RP is up, due to relay 35-1RWK being picked up by the picking up of relay 1RP as will be hereinafter described. Front contact *b* of relay 35LC in the stick circuit for relay 1RP opens the stick circuit, when the control panel is transferred for control of another field location, or when the field location selection is manually cancelled or, as will appear hereinafter, after the controls have been transmitted to the field location 35. (Front contact *b* of relay 35LC also operates in a similar manner in the stick circuit for relay 1NP.)

The depressing of push button 2LPB (FIG. 3b) as described, momentarily closes back contact *a* of the button and relay 2LP is energized over its previously described pickup circuit including front contact *d* of relay 35LC. Relay 2LP accordingly picks up. Front contact *d* of relay 35LC prevents the establishment of the signal control before a field location has been selected; and opens the stick circuit for relay 2LP, when the control panel is transferred for control of another field location, when the field location selection is manually cancelled or, as will appear hereinafter, after the controls have been transmitted to the field location 35. Relay 2LP picks up as stated and is maintained picked up over its previously described stick circuit including back contact *a* of relay 2NP and the front point of its own front contact *a*. This make-before-break contact *a* insures the establishment of the stick circuit for relay 2LP before the back point of contact *a* in the pickup circuit for the relay is opened. The back point of contact *a* of relay 2NP in the stick circuit for relay 2LP provides means for releasing relay 2LP if it had been inadvertently picked up by the operator depressing push button 2LPB incorrectly. (The back point of contact *a* of relay 2NP also provides means for releasing relay 2RP under similar conditions.) The operation of relay 2NP will be discussed hereinafter in this description.

As previously stated, all apparatus being assumed to be in its normal condition, switch 35-1W at field location 35 occupies its normal position and switch indication relay 35-1NWK (FIG. 5), prior to the picking up of relay 35LC, is held up over its previously described stick cir-

cuit including the back point of contact *h* of relay 35LC. When relay 35LC is picked up as previously described, relay 35-1NWK is continued to be held up by the circuit over the front point of contact *h* of relay 35LC and back contact *d* of relay 1NP. Said contact *h* is a make-before-break contact to insure the continued energization of relay 35-1NWK when the said contact transfers from its back to its front contact point. When relay 1RP is picked up as described above, the control pickup circuit for relay 35-1RWK (FIG. 5) including front contact *e* of relay 1RP and front contact *k* of relay 35LC, is completed and relay 35-1RWK picks up. The picking up of relay 35-1RWK establishes the stick circuit for that relay including its own front contact *a* and the front point of contact *h* of relay 35LC. Back contact *d* of relay 1NP in the stick circuits for relays 35-1NWK and 35-1RWK provides the means for releasing both said relays to store a normal switch control when such a control is initiated by the depressing of push button 1NPB and the resultant pickup of relay 1NP.

As has previously been set forth the track diagram illustrated in FIG. 1a is normally dark. However, as shown in FIG. 1b the picking up of relay 35-1RWK completes an intermittent energizing circuit for the filament of indication lamp 35-1WAKE which may be traced from coded battery CB, previously described, over the front point of contact *g* of relay 35-1NWK, front contact *g* of relay 35-1RWK and through the filament of said lamp to terminal N of the battery. Lamp 35-1WAKE thus commences flashing and indicates that a command or control has been stored for controlling switch 35-1W to its reverse position (or that the switch is actually in transit to its reverse position as described later).

The picking up of relay 2LP as previously described completes the previously described control pickup circuit for relay 35-2LHK (FIG. 6) including the front point of contact *c* of relay 2LP, front contact *m* of relay 35LC and the back point of contact *d* of relay 35-2RHK. Relay 35-2LHK accordingly picks up and completes its previously described stick circuits including its own front contact *a*.

The picking up of relay 35-2LHK as described above completes an intermittent energizing circuit for the filament of indication lamp 35-2LBAKE (FIG. 1b) which may be traced from coded battery CB over the back point of contact *c* of relay 35-2HK, the front point of contact *l* of relay 35-2LHK, back contact *k* of relay 35-2RHK, the front point of contact *d* of relay 35-1RWK and through the filament of said lamp to terminal N of the battery. Lamp 35-2LBAKE thus begins to flash and indicates that a control has been stored for clearing signal 35-2LB.

The operator having selected the desired field location 35 and established the proper controls as outlined above, now depresses the code start push button STPB (FIG. 3c) to establish and store a code start for field station 235 assigned to field location 35. The depressing of said push button closes the previously described pickup circuit for relay STP. Accordingly, relay STP picks up and closes its previously described stick circuit including its own front contact *a*, the back point of contact *b* of relay MP and front contact *f* of relay 35LC. Relay STP is accordingly temporarily maintained in its picked-up position, but released when relay MP picks up as hereinafter described. Front contact *f* of relay 35LC in the stick circuit for relay STP opens said stick circuit when the control panel is transferred for control of another field location or when the field location selection is manually cancelled.

The picking up of relay STP closes at its front contact *c* the previously described pick-up circuit for start relay 235ST including front contact *e* of relay 35LC. Relay 235ST accordingly picks up and completes its stick circuit including its own front contact *a* and the back point of contact *c* of field station 235 call relay 235S.

Normally closed back contact *b* of push button STPB over which all start relays such as 235ST are connected to terminal N of the battery is employed for reset purposes, and the pulling of push button STPB will open said contact *b* and release 235ST relay and any other start relays which are picked up. Contact *b* of push button STPB is thus employed in lieu of the reset button shown on the upper right hand side of drawing D-2547, sheet 14A in aforesaid Manual No. 514. It should be pointed out that said contact *b* is also shown connected to terminal 17A of the office line coding unit, in a similar manner that the reset button in said drawing is connected.

The operator by depressing push button STPB completes the storages for field location 35, field station 235, and the control panel is now available to select another location and establish control storages for that location.

It will first be assumed that at the time the operator depresses the start push button STPB, another field station is transmitting indications to the control office over the code control communication system and, therefore, the controls for field location 35 cannot, as previously explained, be transmitted to said location; and that while the said controls are stored by the indication relays, as described above, the operator selects field location 36 to establish control storages to be transmitted to that location.

To select field location 36 the operator need only depress location selection push button 6PB on the control panel as push button 3DPB remains depressed from the previous selection of field location 35. Each group of location selection push buttons on the control panel being interlocked as previously explained, the depressing of push button 6PB returns push button 5PB, previously depressed in the selection of location 35, to its undepressed or normal position. Back contact *d* of push button 5PB (FIG. 2) is therefore opened, opening the pickup circuit for location selection relay 35LC and that relay releases. The pickup circuit for location selection relay 36LC is closed over back contact *d* of push button 6PB and relay 36LC picks up.

The release of relay 35LC opens, at its front contact *b* (FIG. 3a) and its front contact *d* (FIG. 3b) the stick circuits for relays 1RP and 2LP respectively, and these relays release. The release of relay 35LC also opens at its front contact *f* (FIG. 3c) the stick circuit for relay STP and that relay releases. The control panel is now available for the operator to establish control storages for field location 36 in a similar manner that the described control storages for location 35 were established.

The release of relay 35LC transfers the stick circuits for relays 35-1NWK and 35-1RWK (FIG. 5) from the front point of contact *h* of relay 35LC to the back point of that relay and relays 35-1NWK and 35-1RWK remain picked up. Said contact *h* of relay 35LC being a make-before-break contact the opening of the stick circuits to said relays, when the contact is transferring from its front contact point to its back contact point, is prevented. Similarly, the release of relay 35LC transfers the stick circuit for relay 35-2LHK (FIG. 6) from the front point of make-before-break contact *n* of relay 35LC to the back point of said contact and relay 35-2LHK remains picked up. The transfer of these stick circuits also, as is obvious, disconnects the respective relays from the contacts of the function control push button repeater relays, and thereby removes the relays from under the control of the control panel. The controls to be transmitted to field location 35 thus remain stored until the code control communication system is available for transmitting the controls to said location.

It will now be assumed that at the time the operator depresses the start push button STPB as described above, no controls are to be initiated and established for another field station and, therefore, the control panel remains as last described, that is, with push buttons 3DPB and 5PB

depressed. Relay 35LC, therefore, remains picked up at this time.

Relay MP shown in FIG. 4b, picks up, as previously pointed out, when the M or master relay in the office line coding unit of the Form 514 code control communication system picks up. The M relay is not shown in the drawings but it is sufficient for purposes of this description to state that the M relay picks up when a start relay such as 235ST (FIG. 3c) picks up if the communication system is at rest, that is, available for the transmission of control information. Reference is again made to said Manual No. 514 and sheet 14A of drawing D-2547 therein for a description of the operation of the code control communication system. Assuming therefore that the communication system is now available, relay 235ST having been picked up as described, relay M and consequently relay MP picks up. Contact *b* of relay MP in FIG. 3c opens its back contact point, opening the stick circuit to relay STP, which releases after the expiration of its slow release period. However, before front contact *b* of relay STP opens, the previously described circuit, including front contact *f* of relay 35LC and the front point of contact *b* of relay MP, closes momentarily, and since terminal A111 is connected to the cancellation windings or coils UCC and DCC (FIG. 2), these windings become energized momentarily. Push buttons 3DPB and 5PB are therefore actuated to their normal (undepressed) positions, opening the pickup circuit for relay 35LC which releases. The control panel is now in its normal condition and available for selecting another field location. The release of relay 35LC releases relays 1RP and 2LP as described previously, and also opens at its front contact *f* (FIG. 3c) the cancellation circuit just described. Relays 35-1NWK, 35-1RWK, 35-2LHK and 235ST remain picked up as previously described, but the remainder of the apparatus is now in its normal condition.

During the course of the coding action of the code control communication system station call relay 235S (FIG. 4d) is picked up in a manner described in said Manual No. 514. Make-before-break contact *c* of relay 235S (FIG. 3c) transfers the stick circuit for relay 235ST from the back contact point of relay 235S to its front contact point and terminal 8A of the office line coding unit. Relay 235ST is maintained picked up by the circuit from terminal 8A until the station selection portion of the communication code is terminated (8th step of the coding action as described in said Manual No. 514), and the internal circuit in the office line coding unit to terminal 8A is interrupted releasing relay 235ST which is thus returned to its normal position.

When station call relay 235S is picked up, as set forth above, circuits are completed over front contacts *d* and *e* (FIG. 4a) of relay 235S to transmit the stored switch and signal controls to field location 35 during the coding action of the code control communication system. The previously described reverse switch control communication circuit includes front contact *d* of relay 235S, the front point of contact *c* of relay 35-1RWK, front contact *b* of relay 35-1NWK and terminal 3A of the office line coding unit. The previously described control communication circuit for clearing signal 35-2LB includes front contact *e* of relay 235S, the front point of contact *g* of relay 35-2LHK, back contact *g* of relay 35-2RHK and terminal 5A of the office line coding unit. The similarity between these circuits and the circuits to terminals 3A and 5A shown on the upper right hand portion of aforesaid drawing D-2547, sheet 14A, is readily apparent. The desired controls are thus transmitted to field location 35, and relays 35-1NRWSR and 35-2LHSR (FIG. 4a) are controlled to their reverse positions. The similarity between these relays and relays NRWSR and LHSR shown in the lower right-hand portion of aforesaid drawing D-2547, sheet 15A, is also readily apparent. Station call relay 235S is released at the end of the communication control code (16th step in said Form 514 code control communication system) and the above described circuits

70 in the lower right-hand portion of aforesaid drawing D-2547, sheet 15A, is also readily apparent. Station call relay 235S is released at the end of the communication control code (16th step in said Form 514 code control communication system) and the above described circuits

to terminals 3A and 5A of the office line coding unit are opened.

The stored controls having thus been transmitted to field location 35 it is assumed that a control is established at that location for controlling switch 35-1W to its reverse position and the switch commences said movement or is now in transit. It is also assumed, that after the switch has occupied its reverse position signal 35-2LB clears for the desired train movement. The circuits at location 35 for accomplishing these functions are not shown as they form no part of my present invention, but reference can be made to the aforesaid United States Patent 2,698,425, FIGS. 2d and 2e, and description thereof, for an understanding of the operation of the apparatus controlled by contacts of relays 1WS and 2LHS which are respectively similar to relays 35-1NRWSR and 35-2LHSR shown in FIG. 4a of my present drawings.

When a control is established and during the period that switch 35-1W is in transit, as assumed above, relays 35-1NWCR and 35-1RWCR (FIG. 5) are both released and the previously mentioned switch indication circuits to terminals 1 and 3 of the field line coding unit are closed. The circuit to terminal 1 includes the back point of contact *a* of relay 35-1NWCR, back contact *a* of relay 35-1RWCR, and contact *a* of relay 35-1NRWSR in its reverse position. The circuit to terminal 3 includes the back point of contact *b* of relay 35-1RWCR, back contact *b* of relay 35-1NWCR and contact *a* of relay 35-1NRWSR in its reverse position. The energized condition of terminals 1 and 3 is transmitted to the control office by the code communication system and is reflected at the control office by the energized condition of both terminals 9A and 11A of the office line coding unit.

Delivery relay 235D (FIG. 4c) is momentarily picked up by the indication code being received in the control office from field location 35 (16th step of indication code as described in Manual No. 514), and the previously described circuits from terminals 9A and 11A (FIG. 5) are completed over the front points of contacts *a* and *b* respectively, of relay 235D to relays 35-1NWK and 35-1RWK, respectively. The stick circuits for relays 35-1NWK and 35-1RWK are opened at this time at the back points of contacts *a* and *b* respectively of relay 235D, but the indication pickup circuits for said relays being completed over the front points of said contacts, relays 35-1NWK and 35-1RWK, which it will be remembered were both picked up to establish the switch reverse control code, remain picked up. The make-before-break contacts *a* and *b* of relay 235D insure that the circuits over the front points of the contacts are closed before the stick circuits over the back points of the contacts are opened. Relay 235D subsequently releases reestablishing the stick circuits for both relays 35-1NWK and 35-1RWK which thus continue to remain picked up. The indication lamp 35-1WRKE in FIGS. 1a and 1b continues to flash, giving the switch-in-transit indication.

When switch 35-1W at field location 35 has completed its movement to its full reverse position, relay 35-1RWCR (FIG. 5) picks up closing the front point of its contact *b* and opening its back contact *a*. The switch indication circuit to terminal 1 of the field line coding unit at location 35 is, therefore, now open at back contact *a* of relay 35-1RWCR, and the indication circuit to terminal 3 of said unit is transferred from the back point of contact *b* of relay 35-1RWCR to the front point of said contact. The deenergized and energized condition of terminals 1 and 3 respectively, is now transmitted to the control office by the code communication system and is reflected at the control office by the deenergized and energized condition of terminals 9A and 11A, respectively, of the office line coding unit. When delivery relay 235D is now momentarily picked up, relay 35-1RWK remains picked up as before but relay 35-1NWK is released as terminal 9A is deenergized. Relay 235D subsequently releases, relay 35-1RWK remains picked up, and relay 35-1NWK

remains released as its stick circuit is open at its own front contact *a*.

The release of relay 35-1NWK transfers the energizing circuit for the filament of indication lamp 35-1WRKE (FIG. 1b) from the coded battery at the front point of contact *g* of relay 35-1NWK to terminal B of the battery at the back point of said contact and the lamp is steadily illuminated to indicate that switch 35-1W is occupying its reverse position. It will be remembered that it was previously stated that the track diagram is normally dark. However, from the circuit just described it is apparent that a reverse switch indication lamp remains steadily illuminated as long as its respective switch remains in its reverse position. This condition is not considered as a normal condition and the said lamp is maintained illuminated as a reminder to the operator of the position of the switch. No other change in the indication lamp circuits takes place at this time.

As previously stated, relay 35-2LHSR (FIG. 4a) is controlled to its reverse position when the described stored controls are transmitted to field location 35. The movement of the contacts of relay 35-2LHSR to their reverse position deenergizes relay 35-2LASR (FIG. 6). This control circuit for relay 35-2LASR is not shown in the drawings but, this relay is controlled by a contact of relay 35-2LHSR in a manner similar to the control of relay L58ALS by contact 20 of relay L58HS in the previously mentioned Patent 2,580,150 to Earl M. Allen. Relay 35-2LASH is accordingly released. The control of relay 35-2LHSR to its reverse position closes a circuit for supplying energy to terminal 5 of the field line coding unit (FIG. 6). This circuit may be traced from terminal B of the battery over the reverse contact point of contact *a* of relay 35-2LHSR to terminal 5 of said coding unit. The purposes of this circuit will become apparent in the description to follow.

The control of relay 35-2LHSR to its reverse position and subsequent releasing of relay 35-2LASR completes a circuit for controlling 35-2LB to its clear condition. This circuit is not shown in the drawing but such signal control circuits are well known in the art and the circuit may, for example, be similar to the control circuit for signal L58 shown in said FIG. 1b of the above-mentioned Allen patent. The clearing of signal 35-2LB deenergizes relay 35-2LRGPR (FIG. 6) in a manner similar to the deenergization of relay L58RP in FIG. 1b of the Allen patent when signal L58, shown in said FIG. 1b, clears.

Relay 35-2LRGPR accordingly releases and energy is also supplied to terminal 7 (FIG. 6) of the field line coding unit over a circuit extending from terminal B of the battery over back contact *a* of relay 35-2LRGPR to said terminal 7. The release of relay 35-2LRGPR also initiates a code start for transmission of a signal clear indication code from field location 35 to the control office. (Reference is made to the upper right-hand portion of drawing D-2547, sheet 15A, in aforesaid Manual No. 514, for an example of the code starting circuits located at a field location and to the description in said Manual for an understanding of the operation of these circuits).

The code control communication system transmits an indication code and the energized condition of terminals 5 and 7 on the field line coding unit is reflected by the energized condition of terminals 13A and 15A on the office line coding unit. Relay 235D at the control office again momentarily picks up to deliver the indication to the proper relays. Relay 35-2LHK (FIG. 6) which it will be remembered was previously picked up for the transmission of the control for clearing signal 35-2LB, remains picked up when relay 235D picks up as it is then energized over its previously described indication pickup circuit including the front point of contact *c* of relay 235D and the back point of contact *e* of relay 35-2RHK. Contact *c* of relay 235D is a make-before-break contact to insure the continued energization of relay 35-2LHK.

when the contact transfers from its back contact point to its front contact point.

When relay 235D momentarily picks up, the previously described indication pickup circuit for relay 35-2HK, including the front point of contact *e* of relay 235D, the back point of contact *f* of relay 35-2RHK, and the front point of contact *f* of relay 35-2LHK, is completed and relay 35-2HK picks up and closes its front contact *a*.

Relay 235D subsequently releases, again closing the stick circuit for relay 35-2LHK over the back point of contact *c* of relay 235D and the front contact *a* of relay 35-2LHK, and relay 35-2LHK remains picked up. The release of relay 235D also completes the previously described stick circuit for relay 35-2HK including the back point of contact *e* of relay 235D, front contacts *a* and *b* of relay 35-2HK, and back contact *c* of relay 35-2RHK, and relay 35-2HK remains picked up.

The picking up of relay 35-2HK transfers the energizing circuit for the filament of indication lamp 35-2LBAKE (FIG. 1b) from the previously described coded energy at the back point of contact *c* of relay 35-2HK to positive terminal B of the battery connected to the front point of said front contact *c* and the indication lamp is steadily illuminated to indicate that signal 2LB is clear.

Assuming that a train accepts signal 2LB and enters track section 35-1T (FIG. 1a), relay 35-1TKSPR (FIG. 4a) is released closing its back contact *a*. A slotting circuit is thus completed for controlling relay 35-2LHSR to its normal position. This circuit extends from terminal B of the battery over the back point of contact *a* of relay 35-1TKSPR through the lower winding of relay 35-2RHSR and the lower winding of relay 35-2LHSR to terminal N of the battery. Contact *a* of relay 35-2LHSR transfers from its reverse contact point to its normal contact point thereby opening the previously described energizing circuit to terminal 5 of the field line coding unit (FIG. 6). Signal 35-2LB is controlled to its stop condition by the train entering track section 35-1T, relay 35-2LRGPR (FIG. 6) picks up reflecting the stop condition of the signal, and relay 35-2LASR picks up. The picking up of relay 35-2LRGPR opens at the back contact *a* of that relay the previously described energizing circuit to terminal 7 of the field line coding unit. A stop signal indication is now transmitted from the field location to the control office and terminals 13A and 15A (FIG. 6) are deenergized when delivery relay 235D picks up. The stick circuits for relays 35-2LHK and 35-2HK are opened at the back points of contacts *c* and *e*, respectively, of relay 235D when that relay momentarily picks up; and terminals 13A and 15A being deenergized at this time, relays 35-2LHK and 35-2HK release. The release of relay 35-2LHK opens at the front point of its contact 1 (FIG. 1b) the previously described energizing circuit for the filament of signal indication lamp 35-2LBAKE and the lamp is extinguished. The signal control and indication circuits and apparatus are now all again in their normal condition.

I will now assume that after the clearing of signal 35-2LB and before the signal is accepted by a train, the operator discovers that he has mistakenly cleared an improper signal and, therefore, desires to control signal 35-2LB to stop. The operator again selects field location 35 in the same manner as before and picks up relay 35LC (FIG. 2). Now, referring to FIG. 3b, the operator pulls signal control push button 2LPB, thereby closing the previously described pickup circuit for relay 2NP over contact *b* of push button 2LPB. Relay 2NP thus picks up and closes its previously described stick circuit including its own front contact *a*, back contacts *b* of relays 2RP and 2LP, and front contact *d* of relay 35LC. Relay 2NP is thus temporarily maintained in its picked-up position. The operator now depresses starting push button STPB to initiate a start for the transmission of the control for operating signal 35-2LB to its stop condition. Relays STP and 235ST (FIG. 3c) operate in the same manner

as previously described when the signal clear control was to be transmitted.

Referring now to FIG. 6, the pickup of relay 2NP closes at its front contact *c* the previously described control pickup circuit for relay 35-2RHK, which picks up and establishes its previously described stick circuit including its own front contact *a* and the front point of contact *s* of relay 35LC. The pickup of relay 35-2RHK opens at its back contact *e* the stick circuit for relay 35-2HK which releases. Both relays 35-2LHK and 35-2RHK are now picked up and maintained picked up by their stick circuits, and relay 35-2HK is released.

In FIG. 1b, the energizing circuit for the filament of signal indication lamp 35-2LBAKE is open at back contact *k* of relay 35-2RHK and that lamp is extinguished. However, circuits for intermittently energizing the filament of lamps 35-2RBKE and 35-2LBBKE are closed at front contacts *m* of relays 35-2LHK and 35-2RHK. This circuit for the filament of lamp 35-2RBKE extends from coded battery CB over the front contacts *m* of relays 35-2LHK and 35-2RHK in series and through the filament of lamp 35-2RBKE to terminal N of the battery. The circuit for intermittently energizing the filament of lamp 35-2LBBKE extends from coded battery CB over the front contacts *m* of relays 35-2LHK and 35-2RHK in series, the front point of contact *e* of relay 35-1RWK, and through the filament of lamp 35-2LBBKE to terminal N of the battery. Lamps 35-2RBKE and 35-2LBBKE are thus now flashing to give an indication that a signal clear control formerly established has been manually cancelled, and that a control for controlling said signal to stop has been established and that the signal is "in time."

Referring now to FIG. 4a the previously described circuit, including back contact *g* of relay 35-2RHK, for supplying energy to terminal 5A of the office line coding unit, is now open at said back contact *g*. When relay 235S picks up as previously described, no energy will be supplied to terminal 5A and the code control communication system will, therefore, operate to control relay 35-2LHSR to its normal position. The movement of contact *a* (FIG. 6) of relay 35-2LHSR from its reverse contact point momentarily removes energy from terminal 5 of the field line coding unit, but the closing of the normal contact point of contact *a* and the normal contact *b* of relay 35-2LHSR immediately closes a circuit for again supplying energy to said terminal 5. This circuit extends from terminal B of the battery over normal contact *b* of relay 35-2RHSR, normal contact *b* of relay 35-2LHSR, back contact *a* of relay 35-2LASR which remains released until the aforementioned delay period has expired, and over the normal contact point of contact *a* of relay 35-2LHSR to said terminal 5. The controlling of relay 35-2LHSR to its normal position as described above controls signal 35-2LB to its stop condition and relay 35-2LRGPR (FIG. 6) picks up. The picking up of relay 35-2LRGPR opens at back contact *a* of that relay the previously described energizing circuit to terminal 7 of the field line coding unit. However, the above-described energizing circuit including back contact *a* of relay 35-2LASR also extends over the normal contact point of contact *a* of relay 35-2RHSR to said terminal 7 and that terminal is again energized.

A code start for initiating the transmission of an indication code from field location 35 to the control office is established when relay 35-2LRGPR picks up as described, and, after transmission of said code, terminals 13A and 15A of the office line coding unit are energized to reflect the energized condition of said terminals 5 and 7. When relay 235D in the control office picks up, the previously described energizing circuit, for relay 35-2LHK, including the front points of contacts *e* of relay 35-2LHK and 35-2RHK, and terminal 13A, is closed and relay 35-2LHK remains picked up. Similarly, when relay 235D picks up, the previously described energizing circuit for relay 35-2RHK, including the front points

of contacts *f* of relays 35-2RHK and 35-2LHK, and terminal 15A, is closed and relay 35-2RHK remains picked up. Relay 235D subsequently releases re-establishing the stick circuits for relays 35-2LHK and 35-2RHK, including their own front contacts *a*, and the relays remain picked up. Contacts *c* and *d* of relay 235D being make-before-break contacts, continuity of the supply of energy to the windings of relays 35-2LHK and 35-2RHK is insured during the transfer of said contacts from their back to their front contact points or from their front to their back contact points.

Relays 35-2LHK and 35-2RHK, remaining picked up, as described above, no change in the energizing circuits for the filaments of lamps 35-2RBKE and 35-2LBBKE occurs and the lamps continue to flash to give an "in time" indication.

When the delay time at field location 35 has expired, relay 35-2LASR (FIG. 6) is picked up opening at its back contact *a* the previously described energizing circuit for terminals 5 and 7 on the field line coding unit and the terminals are deenergized. The picking up of relay 35-2LASR also initiates a code start at the field location and an indication code is transmitted to the office. Terminals 13A and 15A on the office line coding unit reflect the deenergized condition of said terminals 5 and 7 and, when relay 235D momentarily picks up as before, relays 35-2LHK and 35-2RHK are released opening their front contacts *a*. When relay 235D subsequently releases the stick circuits for relays 35-2LHK and 35-2RHK are thus open and the relays remain released.

The previously described energizing circuits for the filaments of lamps 35-2RBKE and 35-2LBBKE are opened when relays 35-2RHK and 35-2LHK release and the track diagram is now dark except for the continued illumination of reverse switch indication lamp 35-1WRKE as previously described.

It is believed expedient at this time to set forth the purpose of back contacts *d* (FIG. 6) of relays 2LP and 2RP in the previously described circuit from the winding of relay 35-2HK over said contacts to terminal N of the battery. It will be assumed that, as described above, signal 35-2LB has been manually cancelled and relays 35-2LHK and 35-2RHK are picked up indicating the "in time" condition of the signals 35-2L and 35-2R. It will be further assumed that the operator again selects field location 35 on the control panel and establishes a control for reclearing signal 35-2LB by depressing push button 2LPB (FIG. 3b). Relay 2LP is thus picked up in the manner previously described. The picking up of relay 2LP opens at the back point of its contact *c* (FIG. 6) the stick circuit for relay 35-2RHK including the front point of contact *s* of relay 35LC which picked up on the selection of field location 35. Relay 35-2RHK thus releases closing at its back contact *e* (FIG. 6) the pickup circuit for relay 35-2HK. If at this time, due to some change taking place at field location 35, an indication code is transmitted from that location to the office, terminals 13A and 15A on the office line coding unit are energized because signal 35-2LB at location 35 is still "in time." Therefore when delivery relay 235D momentarily picks up closing the front point of its contact *e* (FIG. 6), the pickup circuit from terminal 15A over the front point of contact *f* of relay 35-2LHK and the back point of contact *f* of relay 35-2RHK to the winding of relay 35-2HK is closed. However, relay 35-2HK cannot pick up as its pickup circuit is open at back contact *d* of relay 2LP as previously pointed out. Thus back contact *d* of relay 2LP prevents the picking up of relay 35-2HK and consequently the closing of the signal clear indication circuit over the front point of contact *c* (FIG. 1b) to the filament of lamp 35-2LBAKE. Signal 35-2LB at field location 35 being "in time" it is obvious that said signal clear indication should not be given at this time.

It is also believed obvious that back contact *d* of relay 2RP (FIG. 6) operates in a similar manner to prevent an improper signal clear indication if a control is initiated for clearing signal 35-2R when the signals are "in time."

It will now be assumed that, after the operator has cancelled signal 35-2LB as previously described, it is desired to control switch 35-1W to its normal position. The operator again selects field location 35 on the control panel in the manner previously described and location relay 35LC is picked up. The operator now depresses push button 1NPB (FIG. 3a) closing the previously described pickup circuit for relay 1NP including front contact *a* of relay 35LC and the front point of contact *b* of relay 35-1RWK. Relay 1NP thus picks up and establishes its previously described stick circuit including its own front contacts *a* and *b* and front contact *b* of relay 35LC.

The picking up of relay 1NP opens at its back contact *d* (FIG. 5) the previously described stick circuit for relay 35-1RWK including its own front contact *a* and the front point of contact *h* of relay 35LC. Relay 35-1RWK releases and the previously described circuit for energizing the filament of reverse switch indication lamp 35-1WRKE (FIG. 1b) is opened at front contact *g* of relay 35-1RWK and that lamp is extinguished. Relay 35-1NWK being already released a circuit is completed for intermittently energizing the filament of normal switch indication lamp 35-1WNKE. This circuit extends from coded battery CB, over the back point of contact *f* of relay 35-1NWK, back contact *f* of relay 35-1RWK and through the filament of the lamp to terminal N of the battery. Lamp 35-1WNKE commences to flash to give a "switch-in-transit" indication to the normal position of the switch. (As previously pointed out the switch is not actually in transit at this time but the storage of the normal switch control is considered the equivalent of the switch being in transit).

The release of relay 35-1RWK prepares at the back point of its contact *c* (FIG. 4a) the previously described circuit to terminal 1A of the office line coding unit. The operator now depresses the starting push button STPB and relays STP and 235ST (FIG. 3a) operate in the identical manner previously described to initiate the transmission of the established control to field location 35 (field station 235). When relay 235S (FIG. 4a) picks up as previously set forth the circuit to terminal 1A of the office line coding unit is completed over front contact *d* of relay 235S.

Relay 35-1NRWSR (FIG. 4a) is controlled to its normal position during the course of the coding action of the code control communication system. (Reference is again made to aforementioned Manual No. 514 for an understanding of the operation of said system). A circuit is now closed over a normal contact of relay 35-1NRWSR at location 35 for directing switch 35-1W to its normal position and the switch is assumed to now be in transit from its reverse to its normal position. (Reference is again made to aforesaid Miller Patent 2,698,425, FIGS. 2d and 2e, for an understanding of the controls for thus directing a switch to its normal position.) The movement of switch control relay 35-1NRWSR from its reverse position releases relay 35-1RWCR (FIG. 5) and opens at front contact *b* of the relay the circuit for supplying energy to terminal 3 of the field line coding unit. The circuit to terminal 1 of said unit is now open at contact *a* of relay 35-1NRWSR, as is the circuit over the back point of contact *b* of relay 35-1RWCR to terminal 3 of the unit.

An indication code is initiated at field location 35 by the release of relay 35-1RWCR and the deenergized condition of said terminals 1 and 3 is reflected at the control office by the deenergized condition of terminals 9A and 11A on the office line coding unit. Relay 235D at the control office is momentarily picked up during the

transmission of the indication code but, terminals 9A and 11A being deenergized, relays 35-1NWK and 35-1RWK remain released. The indication lamp circuits in FIG. 1b thus undergo no change and a "switch-in-transit" to the normal position indication continues.

When switch 35-1W completes its movement and occupies its normal position, relay 35-1NWCR (FIG. 5) picks up and supplies energy to terminal 1 of the field line coding unit over the previously described circuit including the front point of contact *a* of said relay. The picking up of relay 35-1NWCR initiates another indication code and the energized condition of terminal 1 is reflected by the energized condition of terminal 9A on the office line coding unit. When relay 235D now picks up during the transmission of the indication code, the previously described indication pickup circuit for relay 35-1NWK is completed over the front point of contact *a* of relay 235D to terminal 9A. Relay 35-1NWK thus picks up and, when relay 235D subsequently releases, relay 35-1NWK is maintained picked over its previously described stick circuit including its own front contact *a* and the back point of contact *h* of relay 35LC.

The picking up of relay 35-1NWK opens at the back point of its contact *f* (FIG. 1b) the previously described energizing circuit to the filament of indication lamp 35-1WNKE and the lamp is extinguished. The track diagram shown in FIG. 1a is now dark and all apparatus is again in its normal condition.

It should be pointed out at this time that the pickup circuits for relays 35-1NWK and 35-1RWK including front contacts *d* and *e*, respectively, of relay 1RP, and the releasing circuits for these relays over back contact *d* of relay 1NP (FIG. 5) also operate as holding circuits to prevent, under some conditions, the destroying of command or control storages stored by said relays. (This discussion also similarly applies to the similar circuits for relays 36-1NWK and 36-1RWK, shown in FIG. 5.) For example, it will be assumed that location 35 has been selected in the manner previously described, switch control push button 1RPB has been actuated to initiate the storage of a reverse switch control for switch 1W at location 35 and, therefore, relays 35-1NWK and 35-1RWK are both picked up to complete the switch command or control storage. It will further be assumed that, at this time, switch 1W at location 35 is in some manner moved from its full normal indication position, such as may happen due to vibration or bad adjustment, etc. The movement of the switch from its normal indication position will release normal switch indication relay 35-1NWCR at said field location (FIG. 5), thereby initiating the transmission of a switch-in-transit indication of the switch from its normal to its reverse position. Terminals 9A and 11A on the office line coding unit are not energized during the transmission of the indication code and, therefore, when delivery relay 235D at the control office momentarily picks up and contacts *a* and *b* of that relay open the stick circuits for relays 35-1NWK and 35-1RWK respectively, no energy is supplied to the windings of these relays from terminals 9A and 11A. However, these relays are prevented from releasing, and thereby destroying the switch control storage for controlling switch 1W to its reverse position, by the holding circuits for the relays including said front contacts *d* and *e* of relay 1RP and contacts *g* and *k* of relay 35LC.

Similar operation to that described above is performed to assure the release of both said indication relays 35-1NWK and 35-1RWK when both relays have been released to store a normal switch control storage for switch 1W and an indication code is received thereafter from field location 35. Such indication code may cause the energization of one or both terminals 9A and 11A of the office line coding units thereby picking up one or both of the indication relays 35-1NWK and 35-1RWK and destroying the normal switch indication storage. How-

ever, back contact *d* of relay 1NP in the stick circuits for said indication relays assures the release of the relays and the continued storage by the relays of the normal switch control storage.

It is believed apparent in view of the above discussion that the push button repeater relays 1NP and 1RP are employed for establishing switch control storages for first switches at a selected location (assume switch 1W at location 35) and for maintaining the established storages until the location selection relay at the selected location has released. After the release of the location selection relay, which reflects that a control code has been initiated, and until the completion of control codes, no indication codes can be transmitted as the communication system is unavailable for the transmission of indication codes. Therefore, at this time, no indication code will be received at the control location from field location 35 to pick up delivery relay 235D and destroy a switch control storage. After the completion of the transmission of the control codes the indication codes will be transmitted and received and the switch control storage will be destroyed. However, this is the proper operation of the system because the switch control has already been transmitted and the storage of said control should thus be terminated.

The manipulations by the operator and the operation of the circuits and apparatus in clearing signal 35-2R over switch 35-1W in its normal or reverse positions, or in clearing signal 35-2LA over switch 35-1W in its normal position, is similar to that described above for controlling switch 35-1W and signal 35-2LB and no description thereof is considered necessary. Similarly, the establishment of controls and operation of the circuits and apparatus in controlling the signals and switch shown at field location 36 is believed readily understood, in view of the above description, and no detailed description is deemed necessary for an understanding thereof. Also the indication lamp circuits shown in FIG. 1b are believed obvious and no further description of these circuits is considered necessary. However, it should be pointed out that the signal indication lamps AKE and BKE in FIG. 1a are in actual practice made two distinctly different colors in order that the operator may readily distinguish between the flashing condition of an AKE lamp and the flashing condition of the corresponding BKE lamp.

From the foregoing description it is apparent that, with the arrangement of apparatus of my invention as shown in the drawings of this application, I have provided means whereby a single set of manual control devices, required for controlling functions at one remotely located field station in a remote control system of the code control communication type, can be employed for controlling functions at a plurality of remotely located field stations in said remote control system, and that this objective is accomplished by employing a minimum of apparatus.

While I have shown and described but one form of apparatus embodying my invention, it is to be understood that various changes and modifications may be made therein within the scope of the appended claims without departing from the spirit and scope of my invention.

Having thus described my invention, what I claim is:

1. A control system for controlling from a first location one or more devices at each of a plurality of other locations, comprising, communication means for transmitting from said first location to each of said other locations commands for controlling the devices and for transmitting from each of said other locations to said first location information reflecting the condition of the devices, storage means at said first location for each device normally responsive to the receipt from the device location of information reflecting the condition of the device for storing an indication of the condition of the device, means for controlling storage of control commands in said storage means, means for initiating the

transmission by said communication means of said commands stored in said storage means; and means controlled by the receipt of information from one of said other locations subsequent to the transmission of one of said commands to such location for restoring the storage means in which said one of said commands is stored to their indication storage function.

2. Apparatus for controlling from a first location a traffic controlling device at a second location by at times transmitting commands from said first location to said second location over an intermittently available communication system over which indications are at other times transmitted back to said first location to provide an indication of the condition of the device, said apparatus comprising, relays at said first location controlled by said indications to different positions to reflect the condition of said device, manually operable means for controlling said relays to positions different from their indication positions to store in the relays commands to be transmitted by the communication system, means effective when a command is stored in said relays for holding the relays in the positions they then occupy to store said command until it can be transmitted to said second location, and manually operable means at said first location for cancelling the stored commands.

3. Apparatus for controlling from a control location a plurality of traffic control devices located at different stations comprising, a communication system for transmitting control commands from the control location to any selected station to control the devices at such station and for subsequently transmitting back to the control location indications of the conditions of the devices at the selected station, indication relays at the control location, means for normally controlling said indication relays by the indications received from the stations to store the indications, means for controlling the indication relays by control commands at the control location to store the commands, means for initiating the transmission by the communication system of the commands stored in the indication relays; and means actuated by an indication received from a station subsequent to the transmission of a command to such station for restoring the indication relays in which the command is stored to their indication storage function.

4. An arrangement for controlling and indicating the position of a two-position device, said arrangement including first and second relays energized and deenergized respectively, and deenergized and energized respectively when the device occupies first and second positions respectively; in combination, a first controller, a second controller, means controlled by said first controller for energizing both said relays when said first controller is operated, means controlled by said second controller for deenergizing both said relays when said second controller is operated, means controlled by said relays when both said relays are deenergized for controlling said device to said first position, means controlled by said relays when both said relays are energized for controlling said device to said second position, means controlled by said device for energizing both said relays when said device is in transit from said first position to said second position, means controlled by said device for deenergizing both said relays when said device is in transit from said second position to said first position, first and second indication lamps, means controlled by said relays for steadily energizing the first indication lamp when said first and second relays are energized and deenergized respectively and for intermittently energizing the lamp when both said relays are deenergized, and means controlled by said relays for steadily energizing the second indication lamp when said first and second relays are deenergized and energized respectively and for intermittently energizing the lamp when both said relays are energized.

5. In a centralized traffic control system for railroads for controlling from a control office a group of traffic

controlling devices at each of a plurality of field locations through the medium of a code type communication system connecting said office with each field location and including a control relay at each field location for each device at the location and at least one indication relay at said control office for each said device for normally storing indications reflecting the position of the associated device, in combination, manually operable controllers, means controlled by said manually operable controllers for selectively controlling said indication relays to store commands for controlling the associated devices, and means controlled by said indication relays for transmitting each stored command over said communication system to the control relay for the associated device.

6. An arrangement for minimizing the number of relays required in a traffic control system of the type in which a plurality of traffic controlling devices are controlled from a central location by means of a code transmitted over a code line and indications of the condition of the traffic controlling devices are transmitted back to the central location over the same code line and in which the transmission of a code necessary to effect a change in a particular device must at times be delayed until after other codes are transmitted, said arrangement comprising a pair of relays at the control location for each traffic controlling device, means controlled by each said device for normally storing in the pair of relays associated with the device information indicative of the condition of the device, manually operable controllers, and means controlled by said controllers for selectively storing in the relays associated with each device information necessary to effect the transmission of a code to control the associated device as soon as the code line becomes available for transmission of such control code.

7. A remote control system of the type having an intermittently available communication system for at times transmitting information from a control location to each of a plurality of remote locations for controlling a plurality of devices at said remote locations and for at other times transmitting information from said remote locations to said control location for indicating the condition of said devices, said system comprising storage means at said control location for each said device, means controlled by each said device for actuating in a first manner the storage means associated with the device to store information indicating the condition of the associated device, manually operable controllers, means controlled by said controllers for actuating in a second manner the storage means associated with a device to store information for controlling the associated device, means controlled by said storage means for controlling said communication system to transmit to the remote locations the last mentioned stored information when said communication system becomes available, and means controlled by each said device for controlling said communication system to transmit to the control location information indicating response of the device to transmitted control information for the device.

8. A system for storing information for indicating and controlling a plurality of two-position devices comprising, a pair of relays for each device, means controlled by each device for controlling the pair of relays associated with the device to first and second combinations of positions to store information reflecting first and second positions respectively of the device, manually operable controllers, and means controlled by said controllers for selectively controlling each pair of relays to third and fourth combinations of positions to store information for controlling the device associated with the pair of relays to said first and second positions, respectively.

9. A system for storing information for indicating and controlling a plurality of two-position devices comprising, a pair of relays for each device, means controlled by each device for controlling the pair of relays associated with

the device to first and second combinations of positions to store information reflecting first and second positions respectively of the associated device, manually operable controllers, means controlled by said controllers for selectively controlling each pair of relays to third and fourth combinations of positions to store information for controlling the device associated with the pair of relays to said first and second positions respectively, and means controlled by each device for controlling the pair of relays associated with the device to said third and fourth combinations of positions to store information reflecting the movement of the device between said first and second positions.

10. A system for storing information for indicating and controlling a pair of two-position devices comprising, three relays for said pair of devices, manually operable controllers, means controlled by said controllers for controlling a first of said relays to a first position to store information for controlling one of said devices to a first position, means controlled by said controllers for controlling a second of said relays to a first position to store information for controlling the other of said devices to a first position, means controlled by one of said devices for controlling the third of said relays to a first position to store information reflecting the first position of said one of said devices, and means controlled by the other of said devices for controlling the third of said relays to a first position to store information reflecting the first position of said other of said devices.

11. A system for storing information for indicating and controlling a pair of devices each controllable at separate times from a first position to a second position comprising, three relays for said pair of devices, manually operable controllers, means controlled by said controllers for energizing a first of said relays to store information for controlling one of said devices from said first to said second positions, means controlled by said controllers for energizing a second of said relays to store information for controlling the other of said devices from said first to said second positions, first means controlled by one of said devices for energizing the third of said relays to store information reflecting the second position of said one of said devices, and second means controlled by the other of said devices for energizing the third of said relays to store information reflecting the second position of said other of said devices.

12. In combination with an intermittently available communication system linking a control location with a plurality of controlled locations for controlling and indicating a plurality of operable functions at each controlled location, a pair of relays at the control location for each said function, means controlled by each said function for controlling the pair of relays associated with the function to a first combination of positions for reflecting a first condition of the function, means controlled by each said function for controlling the pair of relays associated with the function to a second combination of positions for reflecting a second condition of the function, first and second control devices for each said function, means controlled by the first control device for each said function for controlling the pair of relays associated with the function to a third combination of positions for storing a control for operating the function to said first condition, means controlled by the second control device for each said function for controlling the pair of relays associated with the function to a fourth combination of positions for storing a control for operating the function to said second condition, and means controlled by each pair of relays for transmitting the control stored therein to the controlled location of the function associated with the pair of relays when said communication system is available.

13. In combination with a system for controlling and indicating the positions of a remotely located railway track switch over an intermittently available commun-

cation system linking a control point with the location of said switch and including first and second indication relays at said control point for said switch each energized respectively when the switch occupies first and second positions respectively, first and second control devices, means controlled by said first control device for energizing both said relays for storing a control for controlling the switch to said first position, means controlled by said second control device for deenergizing both said relays for storing a control for controlling the switch to said second position, means controlled by said relays for transmitting over said communication system each said stored control to said switch location when said communication system is available, and means controlled by said communication system for restoring said relays to their indicating function when an indication reflecting the response by said switch to a transmitted control is received at said control point over the communication system.

20 14. In combination with a system for controlling and indicating the conditions of a pair of first and second remotely located opposing railway signals over an intermittently available communication system linking a control point with the location of the pair of signals and including first and second relays at said control point energized when the first and second signals respectively are in a cleared condition, first and second control devices, means controlled by said first control device for energizing said first relay for storing a control for clearing said first signal, means controlled by said second control device for energizing said second relay for storing a control for clearing said second signal, means controlled by said relays for transmitting over said communication system each said stored control to said signal location when said communication system is available, a third relay at said control point, and means controlled at separate times by said first and second signals for energizing said third relay when the respective said signal is in a cleared condition and said communication system is available.

30 15. Apparatus for controlling and indicating the positions of a railway switch and a group of railway signals for governing traffic movements over the switch at each of a plurality of locations, comprising a plurality of unit push buttons so interlocked that only one push button can be operated at a time, a plurality of tens push buttons so interlocked that only one push button can be operated at a time, a normal and a reverse switch control push button each biased to a normal position and operable to an actuated position, a right and a left signal control push button each biased to a normal position and operable to an actuated position, electrically operated release means for releasing said tens push buttons and said unit push buttons, a release push button for at times energizing said electrically operated release means, a location selection relay for each of said plurality of locations each energized by operation of a different pair of one of said unit and one of said tens push buttons, first, second and third signal indication relays for each group of signals; means controlled by each location selection relay and the normal switch control push button for controlling the switch indication relays for the switch at the selected location to a first combination of positions when the location selection relay for said location is energized and said normal switch control push button is operated, means controlled by each location selection relay and the reverse switch control push button for controlling the switch indication relays for the switch at the selected location to a second combination of positions when the location selection relay for said location is energized and said reverse switch control push button is operated, means controlled by each location selection relay and the right signal control push button for energizing the first of the signal indication relays for the group of signals at the selected location when the location selection relay for said loca-

tion is energized and said right signal control push button is operated, means controlled by each location selection relay and the left signal control push button for energizing the second of the signal indication relays for the group of signals at the selected location when the location selection relay for said location is energized and said left signal control push button is operated, means controlled by each pair of associated first and second switch indication relays for transmitting to the selected location controls reflecting said first or second combinations of positions of the switch indication relays and thereby controlling the switch at the location to normal or reverse positions respectively, means controlled by each pair of associated first and second signal indication relays for transmitting to the selected location controls reflecting the energized condition of said first or second signal indication relays and thereby controlling the right or left signals respectively at the location to a clear position, means controlled by each said switch for transmitting from the location of the switch indications for controlling the switch indication relays associated with the switch to third or fourth combinations of positions when the switch is controlled to normal or reverse positions respectively, and means controlled by each said group of signals for transmitting from the location of the signals indications for energizing the first and third signal indication relays associated with the signals or the second and third indication relays associated with the signals when the right or left signal respectively is controlled to a clear position.

16. In a system for controlling and indicating at a control point the positions of a group of railway traffic controlling devices at each of a plurality of locations, in combination, a plurality of indication relays at said control point for each device, means controlled by each device for controlling the relays associated with the device to different first combinations of positions for indicating the positions of the device, a controller for each device, and means controlled by each controller for controlling the relays associated with the corresponding device to different second combinations of positions for controlling the positions of the device.

17. In a system for controlling and indicating at a control point over an intermittently available communication system the positions of a group of railway traffic controlling devices at each of a plurality of locations, in combination, a plurality of indication relays at the control point for each device, means controlled by each device for controlling over said communication system the relays associated with the device to different first combinations of positions for indicating the different positions of the device manually operable controllers for each device, means controlled by said controllers for selectively controlling the relays associated with the corresponding device to different second combinations of positions for storing controls for controlling the different positions of the device, and means controlled by said relays for transmitting stored controls to the location of the associated device when said communication system is available.

18. A device having at least two operated positions, a plurality of relays, means controlled by said device for controlling said relays to selectively indicate the position of the device, manually operable controllers, and means controlled by said controllers for selectively controlling said relays to store controls for selectively operating the device.

19. In a system employing a pair of relays controlled to predetermined positions for indicating the positions of a movable device, in combination, manually operable controllers, means controlled by said controllers for selectively controlling said relays to preselected positions different from said predetermined positions for storing controls for controlling the position of the device, and means controlled by said relays for periodically transferring the stored controls to the device.

20. In a system employing a pair of relays controlled

to first and second combinations of positions for indicating first and second positions respectively of a movable device, in combination, first and second manually operable controllers, means controlled by said first and second controllers respectively for controlling said pair of relays to third and fourth combinations of positions respectively for storing controls for controlling the device to said first and second positions respectively, and means controlled by said relays for transferring the stored controls to the device.

21. In a railway track switch control and indication system including a control relay for controlling a switch to normal or reverse positions according as the control relay occupies first or second positions, a normal switch repeater relay controlled from a first to a second position when and only when the switch occupies its normal position, and a reverse switch repeater relay controlled from a first to a second position when and only when the switch occupies its reverse position; in combination, first and second indication relays, means controlled by said normal repeater relay for controlling the first indication relay to first or second positions according as the normal repeater relay occupies first or second positions, means controlled by said reverse repeater relay for controlling the second indication relay to first or second positions according as the reverse repeater relay occupies first or second positions, first and second manual control devices, means controlled by the first device for controlling both indication relays to their first positions for storing a control for controlling said control relay to its first position, means controlled by the second device for controlling both indication relays to their second positions for storing a control for controlling said control relay to its second position; and means controlled by the repeater relays and the control relay for controlling both indication relays to their first positions when both repeater relays occupy their first positions and the control relay occupies its first position, and for controlling both indication relays to their second positions when both repeater relays occupy their first positions and the control relay occupies its second position.

22. In a railway track switch control and indication system comprising, a track switch, a switch control means, first and second switch repeater means, and first and second switch indication means; in combination, a first control device, a second control device, means controlled by the first control device for controlling both indication means to a first position when the first control device is actuated, means controlled by the second control device for controlling both indication means to a second position when the second control device is actuated, means controlled by the indication means for controlling the switch control means to a first position when both indication means occupy their first positions, means controlled by the indication means for controlling the switch control means to a second position when both indication means occupy their second positions, means controlled by the first repeater means for controlling the first indication means to said first position when the first repeater means occupies a first position, means controlled by the second repeater means for controlling the second indication means to said first position when the second repeater means occupies a first position; means controlled by the repeater means and the switch control means for controlling both indication means to said first position when the repeater means both occupy said second position and the switch control means occupies said second position, and for controlling both indication means to said second position when the repeater means both occupy said second position and the switch control means occupies said first position; and indication circuits controlled by the indication means.

23. In a control and indication system for a railway track switch, said system comprising, a track switch, a switch control relay having normal and reverse positions,

means for controlling the switch to its normal and reverse positions when the control relay is controlled to its normal and reverse positions respectively, normal and reverse switch repeater relays energized respectively only when the switch occupies its normal and reverse positions respectively, and a normal and a reverse switch indication relay; in combination, circuit means including a front contact of the normal repeater relay for energizing the normal indication relay, circuit means including a front contact of the reverse repeater relay for energizing the reverse indication relay, circuit means including back contacts of both repeater relays and a reverse contact of the switch control relay for energizing both indication relays, normal switch indication means, reverse switch indication means, circuit means including a back contact of the reverse indication relay and a front or back contact of the normal indication relay for steadily energizing or intermittently energizing the normal switch indication means according as the normal indication relay is energized or deenergized, circuit means including a front contact of the reverse indication relay and a front or back contact of the normal indication relay for steadily energizing or intermittently energizing the switch indication means according as the normal indication relay is deenergized or energized, circuit means including back contacts of both switch indication relays for controlling the switch control relay to its normal position, circuit means including front contacts of both switch indication relays for controlling the switch control relay to its reverse position, manually operable controllers, and means controlled by said controllers for energizing or deenergizing both indication relays according as it is desired to control the switch to its reverse or normal positions respectively.

24. In a centralized traffic control system for railroads for controlling from a control office two railway signals for governing traffic movements over conflicting routes, each signal having a normally energized approach locking relay which becomes deenergized when the respective signal is cleared and which remains deenergized, when the respective signal is manually put to stop, for a predetermined time interval to delay the clearing of the other signal; said traffic control system including a code type communication system linking the control office with the location of the signals; in combination, three indication relays at the control office, manually operable controllers at the control office, means controlled by the controllers for selectively and individually energizing two of the indication relays, means controlled by each energized indication relay and including the communication system for individually and selectively clearing one of said signals, means controlled by each signal and including said communication system for energizing the third of the indication relays when the signal is cleared, first indication means, means controlled by the third of the indication relays and one of said two indication relays in its energized condition for controlling the first indication means to indicate the cleared condition of one of the signals, second indication means, means controlled by the third of the indication relays and the other of said two indication relays in its energized condition for controlling the second indication means to indicate the cleared condition of the other said signals, third and fourth indication means, and means including the communication system and controlled by the signals and said approach locking relays for energizing said two indication relays jointly for controlling the third and fourth indication means to indicate the deenergized condition of the approach locking relays and the signals at stop.

25. In a railway track switch control and indication system comprising, a track switch, a switch control relay having normal and reverse positions, first and second switch repeater relays each having picked-up and released positions, means for controlling the switch to a first position when its switch control relay occupies its

normal position, means for controlling the switch to a second position when the switch control relay occupies its reverse position, means for controlling the first repeater relay to its picked-up position only when the switch occupies its first position, and means for controlling the second repeater relay to its picked-up position only when the switch occupies its second position; in combination, first and second switch indication relays each having picked-up and released positions, first and second manual control devices each having normal and actuated positions, a first pickup circuit for the first indication relay including a front contact of the first repeater relay, a first pickup circuit for the second indication relay including a front contact of the second repeater relay, a second pickup circuit for both indication relays including back contacts of both repeater relays and a reverse contact of the switch control relay, a third pickup circuit for both indication relays including contacts of the first manual control device closed when the device occupies its actuated position, a circuit for maintaining the first indication relay in its picked-up position including one of its own front contacts, a circuit for maintaining the second indication relay in its picked-up position including one of its own front contacts, means for releasing both indication relays including a contact of the second manual control device closed when the device occupies its actuated position, means including back contacts of both indication relays for controlling the switch control relay to its normal position, and means including front contacts of both indication relays for controlling the switch control relay to its reverse position.

26. In an arrangement for indicating the position of two two-position devices, said arrangement comprising a first relay energized when one of the devices occupies a first position and a second relay energized when the other of the devices occupies a first position; in combination, first, second and third manually operable controllers, means controlled by the first controller for energizing the first relay, means controlled by the second controller for energizing the second relay, means controlled by the third controller for energizing the first relay when the second relay is energized, means controlled by the third controller for energizing the second relay when the first relay is energized, means controlled by a front contact of the first relay and a back contact of the second relay for controlling said one device to said first position, means controlled by a front contact of the second relay and a back contact of the first relay for controlling said other device to said first position, a third relay, means controlled by a front contact of the second relay and back contacts of the first relay for energizing the third relay when the first device occupies its said first position, means controlled by a front contact of the first relay and back contacts of the second relay for energizing the third relay when the second device occupies its said first position; first, second and third indication means; means controlled by front contacts of the first and second relays for intermittently energizing the first indication means; means controlled by a front contact of the first relay, a back contact of the second relay, and a contact of the third relay for intermittently or steadily energizing the second indication means according as the third relay is deenergized or energized respectively; and means controlled by a back contact of the first relay, a front contact of the second relay, and said contact of said third relay for intermittently or steadily energizing the third indication means according as the third relay is deenergized or energized respectively.

27. In a centralized traffic control system for railroads, said system including, a control location, a plurality of field locations, a code type communication system linking said control location with each field location and available at separate times for transmitting controls and indications between the control location and each field location, a track switch at each field location, a normal indication relay at the control location for each track switch and

energized by said communication system when each respective switch occupies its normal position, and a reverse indication relay at the control location for each track switch and energized by said communication system when each respective switch occupies its reverse position; in combination, a normal and a reverse manually operative switch control device at said control office, manually operative selective means at the control office for selectively connecting the normal and reverse control devices to each respectively associated normal and reverse indication relay; a memory system for one of the track switches including means controlled by the reverse switch control device for energizing the indication relays associated with said switch and maintaining said relays energized when the location of said switch is selected by the selection means and the reverse control device is operated, and including means controlled by the normal switch control device for deenergizing both said relays and maintaining said relays deenergized when the location of said switch is selected by the selection means and the normal control device is operated; a similar memory system for each other said track switch, switch control means for each track switch, means including said communication system and controlled by front contacts in series of each pair of associated normal and reverse indication relays for controlling the switch control means associated with the pair of associated relays to a reverse position, and means including said communication system and controlled by back contacts in series of each pair of associated normal and reverse indication relays for controlling the switch control means associated with the pair of associated relays to a normal position.

28. In a railway signal control and indication system comprising, first and second opposing signals having associated therewith, first and second signal control relays, first and second normally energized approach locking relays, and first and second normally energized signal repeater relays, respectively; means for deenergizing the first approach locking relay, clearing the first signal, and deenergizing the first signal repeater relay, when the first signal control relay occupies a reverse position; and means for deenergizing the second approach locking relay, clearing the second signal, and deenergizing the second signal repeater relay, when the second signal control relay occupies a reverse position; in combination; first, second, and third indication relays; first, second, and third control devices each having a normally open contact closed when the respective device is actuated; first, second, and third device repeater relays; a circuit including said contact of the first device for energizing the first device repeater relay, a circuit including said contact of the second device for energizing the second device repeater relay, a circuit including said contact of the third device for energizing the third device repeater relay, a first pickup circuit for the first indication relay including a front contact of the first device repeater relay and a back contact of the second indication relay, a circuit including a front contact of the first indication relay and a back contact of the second indication relay for controlling the first signal control relay to a reverse position, a second pickup circuit for the first indication relay including a reverse contact of the signal control relay and a back contact of the second indication relay; a first pickup circuit for the third indication relay including a back contact of the first signal repeater relay, a front contact of the first indication relay, back contacts of the second indication relay, and back contacts of the first and second device repeater relays; a stick circuit for the third indication relay including its own front contacts, a stick circuit for the first indication relay including a back contact of the second device repeater relay and a front contact of the first indication relay, a first pickup circuit for the second indication relay including a front contact of the second device repeater relay and a back contact of the first indication relay, a circuit including a front contact of the second indication relay and a back contact of the first indication relay for

70
75

controlling the second signal control relay to a reverse position, a second pickup circuit for the second indication relay including a reverse contact of the signal control relay and a back contact of the first indication relay; a second pickup circuit for the third indication relay including a back contact of the second signal repeater relay, a front contact of the second indication relay, and back contacts of the first indication relay; a stick circuit for the second indication relay including a back contact of the first device repeater relay and a front contact of the second indication relay; third pickup circuits for both first and second indication relays including normal contacts of the signal control relay, and back contacts of the approach locking relays in multiple; and indication means controlled by contacts of the first, second and third indication relays.

29. In a centralized traffic control system for railroads comprising, a control office, a plurality of field stations, a track switch control relay therefor at each field station, a station selective code type communication system connecting the control office with the field stations, and a normal and a reverse switch indication relay at the control office for each field station; in combination, a normal switch control device, a reverse switch control device, a series of station selection devices, a station selection relay for each field station, circuit means including the station selection devices for energizing at separate times each station selection relay, circuit means including the normal switch control device and front contacts of each station selection relay for deenergizing both indication relays for the field station associated with the station selection relay, circuit means including the reverse switch control device and front contacts of each station selection relay for energizing both indication relays for the field station associated with the station selection relay, circuit means including back contacts of each station selection relay for maintaining both said energized indication relays for the associated station energized, circuit means including back contacts of both indication relays for each field station and said communication system for controlling the track switch control relay at the respective field station to its normal position, circuit means including front contacts of both indication relays for each field station and said communication system for controlling the track switch control relay at the respective field station to its reverse position, a normal switch repeater relay at each field station, a reverse switch repeater relay at each field station, circuit means including a front contact of each repeater relay at each field station and said communication system for energizing each respective switch indication relay; circuit means including back contacts of both repeater relays at each field station and said communication system for deenergizing both switch indication relays for the field station when the track switch control relay at the station is in its normal position, and for energizing both switch indication relays for the field station when the track switch control relay at the station is in its reverse position; and indication means at the control office for each switch for distinctively indicating the switch normal position, the switch reverse position, switch in transit from reverse to normal, and switch in transit from normal to reverse, said indication means controlled by circuits including contacts of the normal and reverse switch indication relays associated with the switch.

30. In a railway track switch control and indication system comprising, a track switch having normal and reverse positions, switch control means having normal and reverse positions, normal and reverse switch repeater means, normal and reverse switch indication means, means for energizing the normal switch indication means when the normal switch repeater means are energized, and means for energizing the reverse switch indication means when the reverse switch repeater means are energized; in combination, means controlled by the switch for energizing the normal switch indication means when the switch is in transit to its reverse position, means

controlled by the switch for energizing said reverse switch indication means when the switch is in transit to its reverse position, first and second operable devices, first and second device repeater means, means controlled by the first device for energizing the first device repeater means when the first device is operated, means controlled by the second device for energizing the second device repeater means when the second device is operated, means controlled by the first device repeater means for energizing the normal switch indication means when the first device repeater means are energized, means controlled by the second device repeater means for maintaining the normal switch indication means energized when the second device repeater means are deenergized, means controlled by the first device repeater means for energizing the reverse switch indication means when the first device repeater means are energized, means controlled by the second device repeater means for maintaining the reverse switch indication means energized when the second device repeater means are deenergized, means controlled by the switch indication means for controlling the switch control means to said normal position when the first and second switch indication means are deenergized, and means controlled by the switch indication means for controlling the switch control means to said reverse position when the first and second switch indication means are energized.

31. In a centralized traffic control system for controlling a plurality of railway signals and switches at each of a plurality of remote locations and for indicating the condition of said signals and switches to a control location, said system including, a code type communication system, a normal switch indication relay at the control location for each switch and energized when the switch occupies its normal position, a reverse switch indication relay at the control location for each switch and energized when the switch occupies its reverse position, and a left and right signal indication relay at the control location for each set of left and right opposing signals respectively; the combination of a control panel comprising a plurality of location selection push buttons, normal and reverse switch control push buttons, and left and right signal control push buttons; a plurality of location selection relays, means controlled by the location selection push buttons for selecting at different times any one of the remote locations and energizing a corresponding one of the location selection relays, means controlled by front contacts of the location selection relays and the reverse switch control push buttons for energizing the normal and reverse switch indication relays for corresponding switches to be controlled to their reverse positions, means controlled by front contacts of the location selection relays and the normal switch control push buttons for deenergizing the normal and reverse switch indication relays for corresponding switches to be controlled to their normal position, means controlled by front contacts of the location selection relays and the left signal control push buttons for energizing the left signal indication relays for corresponding signals to be cleared, means controlled by front contacts of the location selection relays and the right signal control push buttons for energizing the right signal indication relays for corresponding signals to be cleared, means controlled by back contacts of the station selection relays for maintaining the energized switch indication relays and the energized signal control relays in their energized positions, means including the communication system and controlled by front contacts of corresponding energized switch indication relays for transmitting controls for controlling corresponding switches to their reverse position, means including the communication system and controlled by back contacts of corresponding deenergized switch indication relays for transmitting controls for controlling corresponding switches to their normal position, and means including said communication system and controlled by front and back contacts respectively of

corresponding energized and deenergized opposing signal indication relays for transmitting controls for clearing left and right signals in correspondence with said energized signal indication relays.

- 5 32. In a railway signal control and indication system comprising, first and second opposing signals, first and second signal control relays each having normal and reverse positions, first and second signal repeater relays each having energized and deenergized positions, first and second approach locking relays each having energized and deenergized positions, first and second indication relays each having energized and deenergized positions, means for deenergizing the first approach locking relay when the first signal control relay occupies other than its normal position, means for deenergizing the second approach locking relay when the second signal control relay occupies other than its normal position, means for clearing the first signal when the first signal control relay occupies its reverse position and the first approach locking relay is deenergized, means for deenergizing the first signal repeater relay when the first signal is cleared, and means for deenergizing the second signal repeater relay when the second signal is cleared; the combination of, a first control device, a second control device, a third control device, means controlled by the first control device for energizing the first indication relay when the first control device is operated, means controlled by the second control device for energizing the second indication relay when the second control device is operated, means controlled by the third control device for energizing both indication relays when the third control device is operated, means controlled by the first indication relay for controlling the first signal control relay to its reverse position when the first indication relay only is energized, means controlled by the second indication relay for controlling the second signal control relay to its reverse position when the second indication relay only is energized, means controlled by the first signal control relay for energizing the first indication relay when the first signal control relay occupies its reverse position, means controlled by the second signal control relay for energizing the second indication relay when the second signal control relay occupies its reverse position, means controlled by the signal control relays and the approach locking relays for energizing both indication relays when the signal control relays both occupy their normal position and at least one of the approach locking relays is deenergized, a third indication relay having energized and deenergized positions, means controlled by the first signal repeater relay and the first and second indication relays for energizing the third indication relay when the first signal repeater relay and the second indication relay are deenergized, and the first indication relay is energized; means controlled by the second signal repeater relay and the first and second indication relays for energizing the third indication relay when the second signal repeater relay and the first indication relay are deenergized, and the second indication relay is energized; and indication means controlled by contacts of the first, second, and third indication relays.
- 65 33. In a railway signal control and indication system comprising, first and second opposing signals, first and second signal control means, first and second signal repeater means, first and second approach locking means, first and second signal indication means, means for controlling the first approach locking means to a first position when the first signal control means occupies a first position, means for controlling the second approach locking means to a first position when the second signal control means occupies a first position, means for controlling the first signal to a first position when the first signal control means and the first approach locking means occupy said first positions, means for controlling the second signal to
- 70 75

a first position when the second signal control means and the second approach locking means occupy said first positions, means for controlling the first signal repeater means to a first position when the first signal occupies said first position, and means for controlling the second signal repeater means to a first position when said second signal occupies said first position; the combination of, first, second and third control devices; means controlled by the first control device for controlling the first indication means to a first position when the first control device is actuated, means controlled by the second control device for controlling the second indication means to a first position when the second control device is actuated, means controlled by the third control device for controlling both indication means to said first position when the third control device is actuated, means controlled by the first indication means for controlling the first signal control means to a first position when the first indication means only occupies said first position, means controlled by the second indication means for controlling the second signal control means to a first position when the second indication means only occupies said first position, means controlled by the first signal control means for controlling the first indication means to said first position when the first signal control means occupies said first position, means controlled by the second signal control means for controlling the second indication means to said first position when the second signal control means occupies said first position, third signal indication means, means controlled by the first signal repeater means for controlling the third indication means to a first position when the first signal repeater means occupies said first position, means controlled by the second signal repeater means for controlling the third indication means to said first position when the second signal repeater means occupies said first position, means controlled by the signal control means and the approach locking means for controlling both first and second indication means to said first position when both signal control means occupy a second position and at least one of the approach locking means occupies said first position, and indication circuits controlled by the first, second, and third indication means.

34. In a remote control system comprising, a movable device having, a first condition represented by a first extreme position, a second condition represented by a second extreme position, a third condition represented by the device being in transit from said second position to said first position, and a fourth condition represented by the device being in transit from said first position to said second position, a first repeater relay, means for picking up the first repeater relay when and only when the first device is in its said first condition, a second repeater relay, means for picking up the second repeater relay when and only when the first device is in its said second condition, a control relay having a normal and an operated position for selectively controlling said device to said first and third conditions sequentially or to said second and fourth conditions sequentially, a control location, and a communication system linking the control location with said relays, in combination, first and second indication relays at the control location, electrically energized indication means at the control location, means controlled by the first and second repeater relays for controlling the indication relays to energize the indication means selectively to reflect the said first and second conditions of the device, means controlled by the first and second repeater relays and the control relay for controlling the indication relays to energize the indication means selectively to reflect the said third and fourth conditions of the device, manual control means at the control office, means controlled by the manual control means for jointly controlling the indication relays; and means controlled by the indication relays for selectively controlling the control relay to said normal and operated positions.

35. A control system for controlling from and indicat-

ing to a control location four conditions of a plurality of two-position devices located at a plurality of locations remote from the control location, said conditions of each device including a first extreme position, a second extreme position, a first in-transit condition when the device moves from said first extreme position to said second extreme position, and a second in-transit condition when the device moves in the opposite direction; said control system comprising, an intermittently available communication system linking the control location with each remote location; a pair of two-position indication relays at the control location for each two-position device, each pair of relays capable of being controlled to four combinations of positions, namely, the first and second relays energized and deenergized respectively, said first and second relays deenergized and energized respectively, both relays deenergized, and both relays energized; means controlled by the associated two-position device for controlling each pair of relays to a different one of said four combinations of positions when its associated two-position device is in a different one of said four conditions and the communication system is available, a location selection relay at the control location for each remote location, control means for each selection relay, means controlled by each control means for energizing the associated selection relay when controls are to be established for positioning one or more of the two-position devices at the remote location associated with the selection relay, a first and second control device at the control location for each two-position device at a selected remote location, means controlled by the first control device associated with each two-position device for controlling the pair of indication relays associated with the two-position device to one of their said combinations of positions when the location selection relay for the location of the two-position device is energized and the first control device for the two-position device is actuated, means controlled by the last mentioned location selection relay for maintaining the last mentioned pair of indication relays in their said one combination of positions when the last mentioned location selection relay is energized, means controlled by the second control device associated with each two-position device for controlling the pair of indication relays associated with the two-position device to another of their said combinations of positions when the location selection relay for the location of the two-position device is energized and the second control device for the two-position device is actuated, means controlled by the last mentioned location selection relay for maintaining the last mentioned pair of indication relays in said other of their said combinations of positions when the last mentioned location selection relay is energized, means controlled by the indication relays for controlling each two-position device to one of its extreme positions when its associated pair of indication relays are in said one combination of positions and the communication system is available, means controlled by the indication relays for controlling each two-position device to the other of its extreme positions when its associated pair of indication relays are in said other of their said combinations of positions and the communication system is available, a plurality of indication devices at the control location for each pair of indication relays, and means controlled by the indication relays for selectively energizing each plurality of indication devices according to the energized and deenergized conditions of the pair of indication relays associated with the plurality of devices.

36. In combination with a first and a second indication relay for first and second opposing railway signals respectively said relays being deenergized and energized respectively when their associated signals are in their stop and clear conditions respectively, a third indication relay, means controlled by the signals for energizing the third indication relay when either of the signals is in its clear condition, first and second control devices for the

signals, means controlled by the first device for energizing the first indication relay and maintaining the relay energized for storing a control command for clearing the first signal when the second signal is in its stop condition and the first device is actuated, and means controlled by the second device for energizing the second indication relay and maintaining the relay energized for storing a control command for clearing the second signal when the first signal is in its stop condition and the second device is actuated.

37. An arrangement for selecting each group of a plurality of groups of railway switches and signals and for establishing control commands for controlling said switches and signals, said arrangement comprising, a different tens and unit digits designation for each said group, a keyboard, a plurality of unit digit stick push buttons on the keyboard and so interlocked that only one such push button can be depressed at any one time, a plurality of tens digit stick push buttons on the keyboard and so interlocked that only one such push button can be depressed at any one time, a selection relay for each group of switches and signals, means for energizing the corresponding selection relay when a pair of tens and unit digits push buttons corresponding to the said digits designation for the associated group of switches and signals are depressed, a normal and a reverse spring return switch control push button on said keyboard for each switch of the group of switches having the greatest quantity of switches, a pair of right and left spring return signal control push-pull buttons on said keyboard for each set of right and left opposing signals of the group of signals having the greatest quantity of such sets of signals, a normal and a reverse switch control repeater relay respectively for each normal and reverse switch control button, a left and a right signal control repeater relay respectively for each left and right signal control button, a normal signal control repeater relay for each pair of signal control buttons, means for energizing each normal switch control repeater relay when the corresponding one of the normal switch control buttons is pushed and any one of the selection relays is energized, means for energizing each reverse switch control repeater relay when the corresponding one of the reverse switch control buttons is pushed and any one of the selection relays is energized, means for energizing each right signal control repeater relay when the corresponding one of the right signal control buttons is pushed and any one of the selection relays is energized, means for energizing each left signal control repeater relay when the corresponding one of the left signal control buttons is pushed and any one of the selection relays is energized, means for energizing each normal signal control repeater relay when either button of the corresponding pair of signal control buttons is pulled and any one of the selection relays is energized, and means for selectively establishing and storing control commands for controlling the switches and signals when one of the selection relays and at least one of the repeater relays are energized.

38. A switch and signal control command storage system for a track layout having a plurality of switches and signals located at each of a plurality of separate locations in said layout, comprising a miniature diagram of the track layout having distinctive multiple digit location identification symbols included thereon at locations comparable to associated locations in the track layout and having distinctive multiple digit and letter switch and signal identification symbols included thereon at each location at points comparable to associated switches and signals in the track layout, a keyboard having a plurality of manually operable selection push buttons respectively relating to the different characters of the respective digits of said location identification symbols and having a plurality of sets of two manually operable control push buttons each set respectively relating to the different characters of the respective digits and letters of said switch and

signal identification symbols, location selection means for selecting a location and responsive to the manual operation of the push buttons corresponding to the respective digits of the location identification symbols of the respective locations in the track layout and switch and signal selection and control command storage means responsive to the manual operation of the control push buttons corresponding to the respective digits and letters of the switch and signal identification symbols for selecting each switch and signal to be controlled at a selected location and for storing control commands for controlling the selected switch and signal respectively in accordance with the actuated control push button of the respective set of two push buttons associated with the selected switch and the selected signal.

39. In a railway traffic control system for controlling a plurality of switches and signals located at each of a plurality of locations and including a code type communication system connecting a control office with each location and indication relays at the control office for each switch and each signal for receiving through the medium of said communication system and thereafter storing indications of the positions of the switches and the conditions of the signals, in combination, means controlled manually for superseding the stored indications and for storing in the respective indication relays controls for controlling each respective switch and each respective signal, and means controlled by the indication relays for transmitting over said communication system to the respective locations of the switches and signals the respective stored controls when the communication system is available.

40. In an indication system for indicating the stop and clear conditions of each signal of a pair of right and left opposing railway signals and including a right and left relay for said right and left signals respectively, each relay being deenergized when its respective signal is in the stop condition and being energized when its respective signal is in the clear condition, in combination, a third normally deenergized relay, means controlled manually for energizing and maintaining energized said right relay for storing a control command for controlling said right signal to its clear condition, means controlled manually for energizing and maintaining energized said left relay for storing a control command for controlling said left signal to its clear condition, means controlled by said relays for transmitting each stored control command to its respective signal, means controlled by said signals for energizing said third relay for reflecting that one of said respective signals is in its clear condition in response to a transmitted respective control command, a right and a left indication device for the right and left signals respectively, and means controlled by said relays for selectively energizing the devices for selectively indicating the conditions of said signals when at least one of said relays is energized.

41. Apparatus for controlling a plurality of railway switches and signals at a plurality of field locations in a railway track layout comprising at a control location a control panel provided with a plurality of location selection controllers and at least as many switch controllers and signal controllers as the maximum number of switches and signals at any location and a start controller, and also comprising a diagram of the track layout showing the arrangement of the switches and signals at each field location and provided with indication lamps for indicating the normal and reverse positions of each switch and the stop and clear positions of each signal, a code type communication system for transmitting controls and indications between the control location and each field location, a plurality of indication relays at the control location for each switch and signal at each field location, means at the control location actuated by the operation of location selection controllers for a field location for selecting and operatively connecting the switch and signal

indication relays associated with such location with corresponding switch and signal controllers on the control panel, means actuated by the subsequent operation of selected ones of the switch and signal controllers for the selected location for storing in the corresponding switch and signal indication relays associated with such location information reflecting desired positions for corresponding switches and signals at the location, means actuated by the subsequent operation of the start controller for setting into operation the code communication system to transmit to the selected location the information previously stored in said indication relays, means at the selected field location responsive to the receipt of the transmitted information for positioning said corresponding switches and signals, means controlled by said switches and signals at the selected field location for subsequently transmitting over the code communication system to the control location information reflecting the positions said corresponding switches and signals then occupy, means at the control location responsive to the receipt of the last mentioned information for storing in the corresponding indication relays associated with the positioned switches and signals the last mentioned information, and means controlled by the last mentioned indication relays for controlling energization of the corresponding indication lamps on said track layout diagram to indicate the positions of the corresponding switches and signals.

42. In a control and indication system for an operable device having four distinct conditions said system comprising means for controlling the device from its first condition sequentially to its second and fourth conditions, and from its fourth condition sequentially to its third and first conditions according as a control device occupies a first or a second position, first and second indication devices energized and deenergized, or deenergized and energized, according as said operable device is in its first condition or its fourth condition, and both deenergized when the operable device is in its third condition; the combination of, means controlled by said

operable device and said control device for energizing both indication devices when the operable device is in its second condition, a plurality of indication means, and means controlled by the indication devices for selectively energizing said plurality of indication means to distinctly indicate said four distinct conditions of the operable device.

43. In a control and indication system for a railway switch comprising means for controlling the switch to a first or a second position according as a control device occupies a first or a second position, and first and second indication controllers energized and deenergized, or deenergized and energized, according as the switch occupies its first or its second position, and both deenergized when the switch is in transit from its first position to its second position; the combination of, means controlled by said switch and said control device for energizing both said indication controllers when the switch is in transit from its second position to its first position, a plurality of indication means; and means controlled by said indication controllers for selectively energizing said plurality of indication means to distinctly indicate the first position of the switch, the second position of the switch, the in-transit condition of the switch from its first position to its second position, and the in-transit condition of the switch from its second position to its first position.
